[57] ABSTRACT

New 1- and 4-substituted piperidines are stabilizers for organic material. They are produced by reacting corresponding 1-substituted piperidinols with acid chlorides or corresponding 4-substituted piperidines with a compound introducing into the 1-position a residue.

2 Claims, No Drawings

PIPERIDYL CARBOXYLATES

Matter enclosed in heavy brackets [ ] appears in the original patent but forms no part of this reissue specification; matter printed in italics indicates the additions made by reissue.

This is a continuation of application Ser. No. 310,031 filed Nov. 28, 1972, now abandoned.

The present invention relates to new piperidine derivatives, and in particular to new piperidine derivatives substituted at the 1- and 4- positions and having value as stabilisers for polymeric materials.

In German Patent Specification No. 1,929,928 there are described compounds having the general formula:

wherein R_1' and R_2' are the same or different and each is an alkyl group, or, together with the carbon atom to which they are bound, they form a saturated alicyclic group or a group having the formula:

n' is a whole number from 1 to 3 inclusive; and when *n*' is 1, **[R₃]R_j'** is an acyl group derived from an aliphatic, alicyclic or heterocyclic mono-carboxylic acid, an N-substituted carbamoyl group derived from an N-substituted carbamic acid, an N-substituted thiocarbamoyl group derived from an N-substituted thiocarbamic acid, a monovalent group obtained by removing an hydroxyl group from an oxo-acid, an alkyl group, a cycloalkyl group, an aralkyl group, an aryl group or a group having the formula:

wherein R_1' and R_2' have their previous significance; when n' is 2, R_2 is a diacyl group derived from an aliphatic, alicyclic, aromatic or heterocyclic dicarboxylic acid, a dicarbamoyl group derived from a dicarbamic acid, a bis-thiocarbamoyl group derived from a bis-thiocarbamic acid, a carbonyl group, a divalent group obtained by removing two hydroxyl groups from an oxo-acid, an alkylene group, an arylene group, or an arylenedialkylene group; and when n' is 3, $[R_3]$ R_3' is a triacyl group, derived from an aliphatic, alicyclic, aromatic or heterocyclic tricarboxylic acid, a tricar-

bamoyl group derived from tricarbamic acid, a tris-thiocarbamoyl group derived from a tris-thiocarbamic acid, a trivalent group obtained by removing three hydroxyl groups from an oxo-acid, an alkanetriyl group, arenetriyl group or an arenetriyl trialkylene group.

We have now found that certain piperidine derivatives substituted in the 1- and 4-positions are effective stabilisers for polymers, especially against photo- and thermal degradation.

According to the present invention, there is provided a compound having the formula:

and their salts wherein n is 1, 2, 3 or 4; R₁ is a monovalent residue and is an alkyl residue having from 1 to 20, preferably 1 to 12 carbon atoms, an alkenyl or alkynyl residue having from 3 to 20, preferably 3 to 12 carbon atoms, an aralkyl residue having from 7 to 12 carbon atoms, or a residue having the formula:

35 wherein m is 1, 2 or 3; R₄ is hydrogen, methyl or phenyl residue, X₂ is halogen, cyano,

—COR₅, —CO.OR₅, —CO.SR₅, or —CONR₅R₆ and X₁ is hydroxyl, halogen, cyano, —OR₅.

55 wherein R_5 is an alkyl residue having from 1 to 20 carbon atoms, an alkenyl residue having from 2 to 20 carbon atoms, a cycloalkyl residue having from 5 to 12 carbon atoms, an aryl residue having from 6 to 11 carbon atoms, an aryl residue having from 6 to 11 carbon atoms or an aralkyl residue having 7 to 11, preferably 7 to 8 carbon atoms when R_5 is joined to a nitrogen atom, also hydrogen and R_6 is preferably hydrogen or an alkyl residue having from 1 to 4 carbon atoms, or R_5 and R_6 together with the nitrogen atom to which they are bound form a 5- or 6-membered ring which contains no other heteroatoms or contains one or more other heteroatoms, or R_1 is an acyl group

wherein R_7 is hydrogen, an unsubstituted aliphatic or substituted aliphatic residue having from 1 to 20 carbon atoms, an alkenyl or alkynyl residue having from 2 to 20 carbon atoms, a cycloaliphatic residue having from 5 to 12 carbon atoms, an araliphatic residue having from 7 to 14 carbon atoms, an aromatic residue having from 6 to 20, preferably 6 to 12, carbon atoms or an heterocyclic residue, or R_1 is a carbamoyl or thiocarbamoyl residue having the formula:

wherein X_3 is $-\text{O}-$ or $-\text{S}-$, R_8 is hydrogen or an alkyl residue having from 1 to 4 carbon atoms, and R_9 is hydrogen, an alkyl residue having from 1 to 20 carbon atoms, an alkenyl residue having from 3 to 20 carbon atoms, a cycloalkyl residue having from 5 to 12 carbon atoms or an unsubstituted aryl or substituted aryl residue having from 6 to 12 carbon atoms; R_2 is an alkyl residue having from 1 to 4 carbon atoms, an alkenyl or alkynyl residue having 3 to 20 carbon atoms, preferably 3 or 4 carbon atoms, a cycloalkyl residue having from 5 to 12 carbon atoms, an aryl residue having from 6 to 11 carbon atoms or an aralkyl residue having from 7 to 9 carbon atoms or preferably hydrogen; and when n is 1, R_3 is a monovalent radical having the same significance as R_1 , or R_3 represents a monovalent group obtained by removing a hydroxyl group from a sulphonic acid, a sulphonic acid, a phosphorous containing acid or a boric acid, or R_3 is an aryl residue, a cycloalkyl group having from 5 to 12 carbon atoms, or a residue having the formula:

wherein R'_1 is hydrogen or R'_1 has the same significance as R_1 :

When n is 2, R_3 is a divalent residue and is an alkylene residue having from 1 to 20 carbon atoms, an alkenylene residue having from 2 to 20, preferably 3 to 20, carbon atoms, an alkynylene residue having from 2 to 20, preferably 3 to 20, carbon atoms, cycloalkylidene residue having from 5 to 12 carbon atoms, an arylene residue having 6 to 14 carbon atoms, an aralkylene residue having from 8 to 14 carbon atoms or an aliphatic, aromatic or heterocyclic diacyl residue,

an aliphatic or aromatic dicarbamoyl or dithiocarbamoyl residue, sulphinyl or sulphonyl residue or a divalent residue obtained by removing two hydroxyl groups

5

from a disulphonic acid, a phosphorus containing acid or a boric acid.

When n is 3, R_3 is a trivalent residue and is an [arenetriyl] alkanetriyl or an arenetriyl-trialkylene residue, an aliphatic or aromatic triacyl residue or a triacyl residue derived from o-phosphoric, o-phosphorous or o-boric acid; and

when n is 4, R_3 is a tetravalent residue and is an alkane tetrayl residue, or a tetraacyl residue derived from an aliphatic or aromatic tetracarboxylic acid or from o-silicic acid; as well as, when n is 2, 3 or 4, partial ethers, esters and carbamoyloxy and thiocarbamoyloxy compounds related to the fully-reacted compounds of formula I.

When n is 1, R_1 and/or R_3 may be an alkyl residue having from 1 to 20 carbon atoms, preferred 1 to 18, examples of this substituent are methyl, ethyl, n-propyl, n-butyl, sec-butyl, t-butyl, n-hexyl, n-octyl, 2-ethylhexyl, n-nonyl, n-decyl, n-undecyl, n-dodecyl, n-tridecyl, n-tetradecyl, n-hexadecyl or n-octadecyl residue and eicosyl. In terms of accessibility and activity however for optimal compatibility with polyolefines substrates, alkyl substituents R_1 and/or R_3 having from 5 to 20, especially 5 to 12 carbon atoms are preferred. A sub-group of alkyl residues R_1 is that containing from 1 to 4 carbon atoms, preferably methyl.

In those cases in which R_1 and/or R_3 is an alkenyl residue having from 3 to 20 carbon atoms, examples of these substituents are allyl, methallyl, 3-hexenyl, 4-octenyl, 6-decenyl, 10-undecenyl, and 8-octadecenyl residues, however the preferred substituents in this group are allyl and methallyl residues.

When the residues R_1 and/or R_3 are alkynyl they may be for example propargyl, but-1- and -2-ynyl, pent-1-ynyl, hex-1-ynyl, oct-1-ynyl, dec-1-ynyl, dodec-1-ynyl, tetradec-1-ynyl and octadec-1-ynyl. The preferred alkynyl substituents however are propargyl and methylpropargyl.

When R_1 and/or R_3 is an aralkyl residue, suitable examples are benzyl, β -phenethyl, α -methylbenzyl, $\alpha\alpha$ -dimethylbenzyl, α -naphthylmethyl and p-methyl- α -methylbenzyl residues. Benzyl is preferred.

A further sub-group of R_1 and/or R_3 substituents is substituted alkyl derivatives having the formula:

wherein m , R_4 , X_1 and X_2 have their previous significance, but wherein, however, R_4 is preferably hydrogen and m is preferably 1.

When X_1 is an hydroxyl residue, examples of this substituents R_1 and/or R_3 are 2-hydroxyethyl, 2- and 3-hydroxypropyl, 3- and 4-hydroxybutyl, 4-hydroxypentyl and 2-hydroxy-2-phenyl ethyl, preferably 2-hydroxyethyl, 2-hydroxypropyl and 2-hydroxy-2-phenylethyl.

When X_1 and/or X_2 are halogen atoms, examples of R_1 and/or R_3 include 2-chloro- and 2-bromo ethyl, 2- and 3-chloro- and 2- and 3-bromopropyl, 3- and [4-chlorobutyl and 2-chloro-2-phenyl ethyl, preferably 2-chloroethyl, 2-chloropropyl and 2-chloro-2-phenylethyl.

When X_1 and/or X_2 are cyano groups, R_1 and/or R_3 include cyanomethyl, 1- and 2-cyanobutyl, 4-cyano-

pentyl, 2-cyano-2-phenylethyl groups, preferably a 2-cyanoethyl group.

When X_2 is a 1,2-epoxy group, R_1 and/or R_3 may be 2,3-epoxy-n-propyl, 2,3-epoxy-methylpropyl, but the preferred epoxyalkyl substituent is 2,3-epoxy-n-propyl.

When X_1 is $-\text{OR}_5$, $-\text{OCOR}_5$, $-\text{OCSR}_5$, $-\text{OCONR}_6\text{R}_5$, $-\text{CSNR}_6\text{R}_5$, or when X_1 and/or X_2 are $-\text{COR}_5$, $-\text{COOR}_5$, $-\text{COSR}_5$, $-\text{CONR}_6\text{R}_5$ and the group R_5 is alkyl, then the alkyl group preferably has from 1 to 12, most preferred 1 to 2, carbon atoms; when R_5 is an alkenyl residue, then it preferably contains 2 to 4 carbons; when R_5 is a cycloalkyl group it preferably contains 6 carbon atoms; when R_5 is an aryl residue it preferably contains 6 or 7 carbons; and when R_5 is an aralykyl residue, it preferably has 7 or 8 carbon atoms.

R_5 and R_6 together with the nitrogen atom to which they are bound can form a 5- or 6-membered ring such as the pyrrolidinyl-, imidazolidinyl-, pyrazolidinyl-, piperidinyl-, piperazinyl- or morpholinyl ring.

Examples of R_1 and/or R_3 within this sub-group are 2-methoxyethyl, 2-ethoxyethyl, 2-propoxyethyl, 2-butoxyethyl, 2-methoxypropyl, 2- and 3-ethoxypropyl, 2- and 3-n-butoxypropyl, 3- and 4-methoxybutyl, 3- and 4-ethoxybutyl, 3- and 4-butoxybutyl, 4-methoxypentyl, 4-ethoxypentyl, 4-n-butoxypentyl, 2-methoxy-2-phenyl ethyl, 2-ethoxy-2-phenyl ethyl; 2-acetoxymethyl, 2-n-propionoxymethyl, 2-benzoyloxyethyl, 2-acetoxypropyl, 2-n-propionoxypropyl, 4-acetoxymethyl, 4-n-propionoxymethyl, 4-acetoxypentyl, 4-n-propionoxypentyl, 2-phenyl-2-acetoxymethyl, 2-(methylcarbamoyloxyethyl, 2-(phenylcarbamoyloxyethyl, 2-(methylcarbamoyloxyethyl, 2-phenyl-2-(carbamoyloxyethyl, 2-(allylthiocarbamoyloxyethyl, 2-phenyl-2-(methylcarbamoyloxyethyl, 2-phenyl-2-(phenylcarbamoyloxyethyl, methylcarbonylmethyl, 2-(methylcarbonyl)ethyl, 2-(ethylcarbonyl)ethyl, 2-(methylcarbonyl)propyl, and 2-(methylcarbonyl)-2-phenyl ethyl; methoxycarbonylmethyl, 2-(ethoxycarbonyl)ethyl, 2-(methoxycarbonyl)propyl, and 2-(methoxycarbonyl)-2-phenylethyl, 2-(ethylthiocarbonyl)ethyl, 2-(methylthiocarbonyl)propyl and 2-(methylthiocarbonyl)-2-phenylethyl; carbamoylmethyl, 2-carbamoylethyl, 2-methylcarbamoylethyl, 2-ethylcarbamoylethyl, dimethylcarbamoylmethyl, 2-diethylcarbamoylethyl, thiocarbamoylmethyl, 2-(thiocarbamoyl)ethyl, 2-methylthiocarbamoylethyl, dimethylthiocarbamoylmethyl, 2-(phenylcarbamoyl)ethyl.

When n is 1 and R_1 and/or R_3 is an acyl group $-\text{COR}_7$ wherein R_7 is an unsubstituted aliphatic or substituted aliphatic residue having from 1 to 20, preferably 1 to 19, carbon atoms, R_7 may be a methyl, ethyl, propyl, butyl, hexyl, n-octyl, 2-ethylhexyl, n-decyl, n-undecyl, n-tridecyl, n-tetradecyl, n-hexadecyl, n-heptadecyl and eicosyl, chloroethyl, chlorohexyl, methylthioethyl, ethylthioethyl, octylthioethyl, or dodecylthioethyl residue; alkenyl residues R_7 have from 2 to 20, preferably 2 to 17, most preferred 2 to 6, carbon atoms such as vinyl, allyl, methallyl, isobutetyl or hexenyl group; alkynyl residues R_7 have from 2 to 20, preferably 2 to 6, carbon atoms such as a propargyl group; cycloaliphatic residues R_7 have from 5 to 12, preferably 6 to 10, most preferred 6, carbon atoms such as a cyclopentyl or cyclohexyl residue; araliphatic residues R_7 have from 7 to 14, preferably 7 to 13, most preferred 7 to 9, carbon atoms such as a benzyl, β -phenylethyl, diphenylmethyl or styryl residue; unsubstituted aromatic residues R_7 have from 6 to 14, preferably 6 to 10, carbon atoms such

as a phenyl or naphthyl residue, a substituted aromatic residue, substituted by for example alkyl having 1 to 4 carbon atoms such as tolyl, p-tertbutylphenyl; and heterocyclic residues R_7 may be a furan or thiophene residue. Examples of compounds wherein R_1 and/or R_3 are unsaturated acyl groups are preferred those wherein only one of R_1 and R_3 denotes an unsaturated acyl group.

Examples of acyl groups R_1 and/or R_3 are formyl, acetyl, propionyl, n-butyryl, hexanoyl, heptanoyl, octanoyl, 2-ethylhexanoyl, 2,2,4-trimethylpentanoyl, n-decanoyl, n-dodecanoyl, n-tetradecanoyl, n-hexadecanoyl, n-octadecanoyl, n-eicosoyl, acryloyl, α -methacryloyl, crotonoyl, undec-10-enoyl, octadec-9-enoyl, β -methylthiopropionyl, methylthioacetyl, β -octylthiopropionyl, β -dodecylthiopropionyl, cyclopentanoyl, cyclohexanoyl, benzoyl, α - and β -naphthoyl cyclopentylacetyl, cyclohexylacetyl, phenylacetyl, β -phenylpropionyl, diphenyloctyl, β -phenylacryloyl, o-, m- and p-toluoyl, o-, m- or p-methoxybenzoyl and o-, m- and p-chlorobenzoyl, 2-furoyl and 2-picolinoyl.

When n is 1, R_1 and/or R_3 may also be a carbamoyl or thiocarbamoyl residue having the formula:

wherein X_3 is $-\text{O}-$ or $-\text{S}-$, R_8 is hydrogen or an alkyl residue having from 1 to 4 carbon atoms and R_9 is hydrogen, an alkyl residue having from 1 to 20, preferably 1 to 8, carbon atoms, an alkenyl residue having from 3 to 20 carbon atoms, a cycloalkyl residue having from 5 to 12 carbon atoms or an unsubstituted [alkyl] aryl, or substituted aryl, for instance, alkyl or halogen-substituted aryl residue having from 6 to 12, preferably 6 to 10, carbon atoms. Examples of suitable residues within this group are carbamoyl, N-methylcarbamoyl, N-ethylcarbamoyl, N-n-propylcarbamoyl, N-isopropylcarbamoyl, N-n-butylcarbamoyl, N-n-pentylcarbamoyl, N-n-octylcarbamoyl, N-n-decylcarbamoyl, N-n-dodecylcarbamoyl, N-n-octadecyl, N-n-eisocylcarbamoyl, N-allylcarbamoyl, N-methallylcarbamoyl, N-undecenylcarbamoyl, N-cyclopentylcarbamoyl, N-cyclohexylcarbamoyl, N-methylcyclohexylcarbamoyl, N-cyclododecylcarbamoyl, N-(1- and 2-perhydronaphthyl)-carbamoyl, N-adamantylcarbamoyl, N-cyclopentylmethylcarbamoyl, N-benzylcarbamoyl, N-(β -phenethyl)carbamoyl, N-(1- and 2-naphthylmethyl)carbamoyl, N-phenylcarbamoyl, N-(o-, m- and p-tolyl)carbamoyl, N-(2,4- and 2,6-xylyl)carbamoyl, N-(α - and β -naphthyl)carbamoyl, N,N-dimethylcarbamoyl, N-methyl, N-ethylcarbamoyl, N,N-diethylcarbamoyl, N,N-diisopropylcarbamoyl, N,N-di-n-propylcarbamoyl, N,N-di-n-butylcarbamoyl and N,N-di-isobutylcarbamoyl residues as well as the corresponding thiocarbamoyl residues.

When R_2 is an alkyl residue it is for example methyl, ethyl, n-propyl, isopropyl, n-butyl, isobutyl, t-butyl, preferably methyl, as alkenyl residue R_2 is for example allyl, methallyl, 3-hexenyl, 4-octenyl, 6-decenyl, 10-undecenyl or 8-octadecenyl, preferably allyl or methallyl and as alkynyl residue for example propargyl, but-1- and -2-ynyl, penta-1-ynyl, hex-1-ynyl, oct-1-ynyl, dec-1-ynyl, dodec-1-ynyl, tetradec-1-ynyl and octadec-1-ynyl, preferably propargyl, R_2 as cycloalkyl is for example

cyclopentyl, cyclohexyl, cyclooctyl, cyclododecyl, preferably cyclohexyl as aryl residue R_2 is for example phenyl, p-tolyl, t-butylphenyl, naphthyl, preferably phenyl or p-tolyl and as aralkyl residue it is for example benzyl, alpha-methylbenzyl, p,alphadimethylbenzyl, preferably benzyl.

When n is 1

R_3 may be the same as R_1 . If R_3 is alkyl it is preferably an alkyl group having from 3 to 18 carbon atoms.

When R_3 represents an aryl residue it is for example an aromatic residue having 6 to 20 carbon atoms, preferably an aryl residue having 6 to 12 carbon atoms, most preferred phenyl.

When n is 2

R_3 is, for example an alkylene residue having from 1 to 20, preferably 2 to 6, carbon atoms such as methylene, ethylene, trimethylene, tetramethylene or hexamethylene residue. Alkenylene residues R_3 preferably contain 3 to 20, most preferred 3 or 4 carbons, and may be, for instance a 1,3-propene or 1,4-butene-2-ene residue. Alkynylene residues R_3 preferably contain 3 to 20, most preferred 4 carbon atoms and may be, for instance a 1:4 but-2-ynylene residue. When R_3 is a cycloalkylidene residue, it preferably contains 7 or 8 carbon atoms, for instance a cyclohexyldimethylene residue.

When R_3 is arylene it has preferably 6 to 12 carbon atoms and it may be for example 1,3-phenylene, or 4,4'-diphenylene.

When R_3 is aralkylene it may be for example α,α -p-xylylene.

Diacyl residues R_3 include those derived from an aliphatic, aromatic or heterocyclic dicarboxylic acid. Examples of aliphatic dicarboxylic acids are those having from 2 to 20, preferably alkan dicarboxylic acids having 6 to 10 carbon atoms such as malonic, succinic, glutaric, adipic, pimelic, suberic, azelaic, sebacic, 1,12-dodecanedioic, 1,18-octadecanedioic, 1,20-docosanedioic acid and N-methylimino diacetic acid. Examples of aromatic diacyl residues are those derived from phthalic, isophthalic and terephthalic acids, each optionally ring-substituted, for instance by halogen, an alkyl or alkoxy group each having from 1 to 20 carbon atoms, a hydroxy or tertiary amino group.

Examples of heterocyclic dicarboxylic acids are 2,5-thiophene dicarboxylic acid or 2,5-furandicarboxylic acid.

R_3 is for example an aliphatic or aromatic dicarbamoyl residue such as a divalent [alkyl] alkylene dicarbamoyl residue for example the divalent residue of butan-1,4-dicarbamoyl or hexan-1,6-dicarbamoyl or such as a divalent [aryl] arylene dicarbamoyl residue such as the divalent residue of [phenyl] phenylene-1,4-dicarbamoyl. R_3 is for example an aliphatic or aromatic dithiocarbamoyl residue such as a divalent [alkyl] alkylene dithiocarbamoyl residue for example the divalent residue of butan-1,4-dithiocarbamoyl or hexan-1,6-dithiocarbamoyl or such as an divalent [aryl] arylene dithiocarbamoyl residue sue as the divalent residue of [phenyl] phenylene-1,4-dithiocarbamoyl.

When n is 3

R_3 is, for instance, a triacyl group derived from an aliphatic tricarboxylic acid such as nitrilotriacetic acid, tricarballylic acid, from an aromatic tricarboxylic acid such as benzene tricarboxylic acid or from an inorganic

acid such as o-phosphorous, o-phosphoric or o-boric acid, or oxyacids, for example, benzene-1,3,5-trisulphonic acid.

When n is 4

R_3 is, for instance, a tetracyl group derived from a tetracarboxylic acid, such as ethylene diamine, tetracarboxylic acid, from the tetracarboxylic acids described in British Patent Specification No. 1080335, 1,2,4,5,-benzene tetracarboxylic acid or from o-silicic acid.

R_3 preferably represents an acyl or an N- substituted carbamoyl, an alkylene group, a substituted alkylene or an aralkyl group.

R_1 preferably represents an alkyl, alkenyl, or substituted alkyl group such as hydroxyalkyl, alkylcarbonyloxy or aralkyl group.

Examples of compounds of the present invention are:

Examples where n=1

- 5 Tris(1,2,2,6,6-pentamethyl-4-piperidinyl)tricarballylate
- Tris(1,2,2,6,6,4''4-piperidinyl)trimesate
- Tris(1,2,2,6,6-pentamethyl-4-piperidinyl)trimellitate
- Tris(1,2,2,6,6-pentamethyl-4-piperidinyl)phosphite
- Tris(1,2,2,6,6-pentamethyl-4-piperidinyl)phosphate
- 10 Tris(1,2,2,6,6-pentamethyl-4-piperidinyl)borate
- Tris(1-n-octadecyl-2,2,6,6-tetramethyl-4-piperidinyl)trimesate
- Tris(1-allyl-2,2,6,6-tetramethyl-4-piperidinyl)phosphite
- Tris(1-propargyl-2,2,6,6-tetramethyl-4-piperidinyl)borate
- Tris(1-benzyl-2,2,6,6-tetramethyl-4-piperidinyl)trimellitate
- Tris[1-(2'-hydroxyethyl)-2,2,6,6-tetramethyl-4-piperidinyl]trimesate
- 20 Tris[1-(2'-cyanoethyl)-2,2,6,6-tetramethyl-4-piperidinyl]phosphite
- Tris[1-acetyl-2,2,6,6-tetramethyl-4-piperidinyl]borate
- Tris[1-methylcarbamoyl-2,2,6,6-tetramethyl-4-piperidinyl]trimesate

Examples where n=4

- Tetrakis(1,2,2,6,6-pentamethyl-4-piperidinyl)ethylenediamine tetracarboxylate
- Tetrakis(1,2,2,6,6-pentamethyl-4-piperidinyl)pyromellitate
- 30 Tetrakis(1,2,2,6,6-pentamethyl-4-piperidinyl)o-silicate
- Tetrakis(1-n-octyl-2,2,6,6-tetramethyl-4-piperidinyl)pyromellitate
- Tetrakis(1-allyl-2,2,6,6-tetramethyl-4-piperidinyl)pyromellitate
- Tetrakis(1-propargyl-2,2,6,6-tetramethyl-4-piperidinyl)o-silicate
- Tetrakis(1-benzyl-2,2,6,6-tetraethyl-4-piperidinyl)ethylenediamine tetracarboxylate
- 40 Tetrakis[1-(2'-hydroxypropyl)-2,2,6,6-tetramethyl-4-piperidinyl]o-silicate
- Tetrakis[1-stearoyl-2,2,6,6-tetramethyl-4-piperidinyl]pyromellitate
- Tetrakis[1-phenylcarbamoyl-2,2,6,6-tetramethyl-4-piperidinyl]o-silicate
- The invention also includes salts of the compounds of Formula I, for instance salts of inorganic acids such as phosphates, carbonates, sulphates and chlorides and salts of organic acids such as acetates, stearates, maleates, citrates, tartrates, oxalates, benzoates and substituted carbamic acids.

Examples of salts are

- 4-n-butoxy-1,2,2,6,6-pentamethylpiperidine dihydrogen phosphate
- 55 4-n-dodecyloxy-1,2,2,6,6-pentamethylpiperidine hydrochloride bis(1,2,2,6,6-pentamethyl-4-piperidinyl)sebacate sulphate
- 1,2,2,6,6-pentamethylpiperidinyl-4-beta-(3',5'-di-t-butyl-4'-hydroxyphenyl)propionate.bicarbonate
- 60 4-methylcarbamoyloxy-1,2,2,6,6-pentamethylpiperidine.acetate
- 1,6-bis(4'-carbamoyloxy-1',2',2',6',6'-pentamethylpiperidine hexane stearate
- 65 4-phenyl carbamoyloxy-1,2,2,6,6-pentamethylpiperidine.benzoate
- 1,2,2,6,6-pentamethylpiperidinyl-4-n-octanoate 3',5'-di-t-butyl-4'-hydroxybenzoate

- 1,4-bis(1',2',2',6',6'-pentamethyl-4'-piperidyloxy)butane hydrogen oxalate
 4-(2'-cyanoethoxy)1,2,2,6,6-pentamethylpiperidine hydrogen maleate
 4-stearylcarbamoyloxy-1,2,2,6,6-pentamethylpiperidine.citrate
 1-(2'-hydroxyethyl)-2,2,6,6-tetramethylpiperidinyl-4-n-octanoate.tartrate
 1,2,2,6,6-pentamethylpiperidinyl-4-benzoate.dibutyl carbamate.

R_1 or R_3 can be represented by a monovalent, divalent or trivalent group obtained by removing 1 to 3 hydroxyl groups from a sulphonic acid, a sulphinic acid, a disulphonic acid, a phosphorus containing acid, such as o-phosphoric or o-phosphorous acid or a boric acid. The following list shows compounds with acid radicals for R_3 . However, the same radicals are also examples for R_1 .

a. when n is 1

- 1,2,2,6,6-pentamethylpiperidinyl-4-benzene sulphinate
 1,2,2,6,6-pentamethylpiperidinyl-4-benzene sulphonate
 1,2,2,6,6-pentamethylpiperidinyl-4-methyl sulphate
 1,2,2,6,6-pentamethylpiperidinyl-4-dimethylborate
 1,2,2,6,6-pentamethylpiperidinyl-4-phenyl phosphonate
 1,2,2,6,6-pentamethylpiperidinyl-4-dimethyl phosphite
 1,2,2,6,6-pentamethylpiperidinyl-4-diphenyl phosphate

b. when n is 2

- bis(1,2,2,6,6-pentamethyl-4-piperidinyl)sulphate
 bis(1,2,2,6,6-pentamethyl-4-piperidinyl)phosphonate
 bis(1,2,2,6,6-pentamethyl-4-piperidinyl)phenyl phosphate

- bis(1,2,2,6,6-pentamethyl-4-piperidinyl)benzene-1,3-disulphinate

c. when n is 3

- tris(1,2,2,6,6-pentamethyl-4-piperidinyl)-benzene-1,3,5-trisulphonate
 tris(1,2,2,6,6-pentamethyl-4-piperidinyl)-benzene-1,3,5-trisulphinate.

A preferred sub-group of compounds of formula 1 are those compounds having the formula:

and their salts, wherein Y is an alkyl group having from 1 to 20, preferably 1 to 4, carbon atoms, alkenyl having from 3 to 20 carbon atoms or an aralkyl residue, preferably having from 7 to 9 carbon atoms, and n_1 is 1 or 2; when n_1 is 1, R is hydrogen or a monovalent aliphatic residue having from 1 to 20, preferably 6 to 20 carbon atoms, a monovalent alicyclic residue having from 5 to 12 carbon atoms, or a monovalent aromatic residue having from 6 to 20 carbon atoms; or

and when n_1 is 2, R is a divalent aliphatic residue having from 1 to 20, preferably 4 to 20 carbon atoms, a divalent alicyclic residue having from 5 to 12 carbon atoms or a divalent aromatic residue having from 6 to 14 carbon atoms. Two sub-groups of the compounds of the formula Ia are those having as Y alkyl from 1 to 4 carbon atoms and alkyl having 5 to 20 carbon atoms.

Examples of substituents Y are methyl, ethyl, n-propyl, isopropyl, n-butyl, sec.butyl, n-hexyl, n-octyl, n-dodecyl, n-octadecyl, eicosyl, allyl, methallyl, oleyl, benzyl, α -methylbenzyl, p-methylbenzyl and p-methyl- α -methylbenzyl. However, it is particularly preferred that Y is methyl.

When n_1 is 1, R can be hydrogen, methyl, ethyl, n-propyl, isopropyl, n-butyl, sec.butyl, t-butyl, n-pentyl, 1-ethylpropyl, 2-methylbutyl, n-hexyl, 2-methylpentyl, n-heptyl, 2-ethylpentyl, n-octyl, 2,2,4-trimethylpentyl, n-decyl, n-undecyl, n-tridecyl, n-pentadecyl, n-heptadecyl, eicosyl, vinyl α - or β -methylvinyl, dec-9-enyl, heptadec-8-enyl, β -methythioethyl, β -octylthioethyl, β -dodecylthioethyl, cyclopentyl, cyclohexyl, cyclohex-3-enyl, methylcyclohexyl, t-butylcyclohexyl, cyclododecyl, 1- or 2-perhydronaphthyl, adamantlyl, cyclopentylmethyl, cyclohexylmethyl, β -cyclohexylethyl, 1- or 2-(perhydronaphthyl)methyl, β -1- or 2-perhydronaphthyl[ethyl, benzyl, β -phenylethyl, β -phenylvinyl, 1- or 2-naphthylmethyl, β -[1- or 2-naphthyl]ethyl, phenyl, o-, m- or p-tolyl, o-, m- or p-ethylphenyl, o-, m- or p-isopropylphenyl, o-, m- or p-t-butylphenyl, phenylphenyl, 4-methyl-1-naphthyl, 4-ethyl-1-naphthyl, 4-isopropyl-1-naphthyl or 4-t-butyl-1-naphthyl or the group

Particularly preferred substituent groups R are those listed above containing from 6 to 20 carbon atoms, as well as the group having the formula:

wherein R_{10} and R_{11} are the same or different and each is an alkyl group having from 1 to 6, preferably 1 to 4 carbon atoms such as methyl, ethyl, n-propyl, isopropyl, sec.butyl, t-butyl, t-pentyl, (1,1-dimethylpropyl), t-hexyl (1,1-dimethylbutyl), but preferably methyl, isopropyl or t-butyl groups: A is $-CH_2-$.

60 A is $-CH_2-$, $-CH_2CH_2-$ and p is 0 or 1.

When n_1 is 2, R can be methylene, 1,2-ethylene, 1,4-n-butylene, 1,8-n-octylene, 2,2,4-trimethyl-1,4-butylene, 1,10-n-decylene, 1,2-eicosylene, vinylene, propylene, 1,2-, 1,3- and 1,4-cyclohexylene, cyclohexyl-3-ene, 11,2-, 1,3- and 1,4-phenylene, p-xylylene, 1,4-

and 1,5-naphthylene, diphenylene or diphenylmethylen.

Specific examples of compounds having the formula Ia are shown on the preceding pages [to].

A further preferred sub-group of compounds of formula I are those having the formula: 5

and is salts wherein Y_1 is an alkyl residue having from 1 to 12 carbon atoms, an alkenyl residue having from 3 to 12 carbon atoms or an aralkyl residue having from 7 to 9 carbon atoms and R_{12} is hydrogen or an alkyl or alkenyl containing up to 20 carbon atoms, and substituted alkyl having the formula 20

wherein m is 1, 2 or 3,
 R₄ is hydrogen or methyl,

X_1 is halogen or methoxy and

X_2 is halogen or R_{12} is an alkenyl or alkenylen having up to 20 carbon atoms, a cycloalkyl or cycloalkyliden having 5 to 12 carbon atoms, an aryl or arylen having 6 to 12 carbon atoms and q is 1 or 2.

Two sub-groups of compounds of the formula Ib are 35 those having as Y_1 alkyl from 1 to 4 and alkyl having 5 to 12 carbon atoms.

When q is 1, R_{12} can be for example hydrogen, methyl, ethyl, n-propyl, isopropyl, n-butyl, secbutyl, t-butyl, n-pentyl, 2-ethylpropyl, 2-methylbutyl, n-hexyl, 40 2-methylpentyl, n-heptyl, 2-ethylpentyl, n-octyl, 2-ethylhexyl, 2,2,4-trimethylpentyl, n-decyl, n-dodecyl, n-tetradecyl, n-octadecyl, eicosyl, mesityl, allyl, oleyl, cyclopentyl, cyclohexyl, methylcyclohexyl, t-butylcyclohexyl, t-octylcyclohexyl, cyclododecyl, 1- and 2-per- 45 hydronaphthyl, adamanyl, cyclopentylmethyl, cyclohexylmethyl, β -cyclohexylethyl, benzyl, $[\beta$ -Phenylethyl] β -phenylethyl, 1- and 2-naphthylmethyl, β [1- and 2-naphthyl]ethyl, phenyl, o-, m- and p-tolyl, 2,4- and 2,6-xylyl, phenyl, o-, m- and p-tolyl, 2,4- and 2,6-xylyl, p-chlorophenyl, 3-chloro-p-tolyl, o-ethylphenyl, p-t-butylphenyl, 2,3- and 2,5-di-chlorophenyl, α - and β -naphthyl, phenylphenyl. Preferred monovalent groups R_{12} are hydrocarbyl groups such as methyl, ethyl, propyl, isopropyl, n-butyl, 2-ethylhexyl, dodecyl, 55 octadecyl, allyl, oleyl, cyclohexyl, benzyl, phenyl, o-, m- and p-tolyl, 2,4- and 2,6-xylyl and naphthyl.

When q is 2, R_{12} can be for example methylene, 1,2-ethylene, 1,4-n-butylene, 1,6-n-hexylene, 1,8-n-octylene, 2,4,4-trimethyl-1,6-hexylene, 1,10-n-decylene, 1,2-eicosylene, 1,2-eicosylene, 1,3- and 1,4-cyclohexylene, 1,3- and 1,4-phenylene, 2,4-tolylene, 1,5-naphthylene, 4,4'-diphenylene, 4'-diphenylemethylen, 3,3'-dimethyl-4,4'-diphenylene, 3,3'-dimethyl-4,4'-diphenylmethylen.

Preferred divalent groups R_{12} are 1,2-ethylene, 1,6-hexylene, 2,4,4-trimethyl-1,6-hexylene, 1,3- and 1,4-phenylene, 2,4-tolylene, 1,5-naphthylene, 4,4'-diphenylmethylen.

In the above formula Ib, examples of the group Y_1 are methyl, ethyl, n-propyl, isopropyl, n-butyl, secbutyl, n-hexyl, n-octyl, n-dodecyl, allyl, α -methylallyl, 10-undecenyl, benzyl, α -methylbenzyl, p-methylbenzyl, p-methyl- α -methylbenzyl, α -naphthylmethyl. Particularly preferred are straight or branched alkyl having 1 to 4 carbon atoms and for reasons of ease of preparation the most preferred meaning for Y_1 is methyl.

Specific examples of the carbamoyloxy derivatives of 10 N-substituted-2,2,6,6-tetrasubstituted piperidin-4-ols of formula **[Ic]** **lb** are given in the preceding pages [19 and 20] R_3' .

The following groups A to O are subgroups of compounds of the formula I.

15 A. Compounds of formula I wherein when n is 1, R₃ is a monovalent residue and is an alkyl residue having from 1 to 20 carbon atoms, a cycloalkyl residue having from 5 to 12 carbon atoms, an alkenyl or alkynyl residue having from 3 to 20 carbom atoms, an aralkyl residue having from 7 to 12 carbon atoms, or a residue having the formula:

wherein m is 1, 2 or 3, R₄ is a hydrogen, methyl or phenyl residue, X₂ is halogen, cyano,

—COR₅, —CO.OR₅, —CO.SR₅ or —CONR₅R₆ and
 30 X₁ is hydroxyl, halogen, cyano, —OR₅,

wherein R₅ is an alkyl residue having from 1 to 20 carbon atoms, an alkenyl residue having from 2 to 20 carbon atoms, a cycloalkyl residue having 5 to 12 carbon atoms, an aryl residue having from 6 to 11 carbon atoms or an aralkyl residue having 7 to 14 carbon atoms or when R₅ is joined to a nitrogen atom, also hydrogen and R₆ is hydrogen or an alkyl residue having from 1 to 4 carbon atoms, or R₅ and R₆ together with the nitrogen atom to which they are bound form a 5- or 6-membered ring which contains no other heteroatoms or contains one or more other heteroatoms or R₃ is an aryl residue or a residue having the formula:

wherein R_1' is hydrogen or R_1' has the same significance as R_1 of formula I; when n is 2, R_3 is a divalent residue and is an alkylene residue having from 1 to 20 carbon atoms, an alkenylene residue having from 2 to 20 carbon atoms, an alkynylene residue having from 2 to 20 carbon atoms, a cycloalkyliden residue having from

21

3 to 12 carbon atoms, an arylene residue having 6 to 14 carbon atoms; when n is 3, R₃ is a trivalent residue and is an alkanetriyl, an arenetriyl or an arenetriyltrialkylene residue, and when n is 4, R₃ is a tetravalent residue and is an alkanetetrayl residue.

B. Compounds of the formula I wherein when n is 1 R₃ is an acyl group

wherein R₇ is hydrogen, an unsubstituted aliphatic or substituted aliphatic residue having from 1 to 20 carbon atoms, an alkenyl or alkynyl residue having from 2 to 20 carbon atoms, a cycloaliphatic residue having from 5 to 12 carbon atoms, an araliphatic residue having from 7 to 14 carbon atoms, an aromatic residue having from 6 to 20 carbon atoms, or an heterocyclic residue, or R₃ represents a monovalent group obtained by removing a hydroxyl group from a sulphinic acid, a sulphonic acid, a phosphorus containing acid or a boric acid, when n is 2, R₃ is a divalent residue of an aliphatic, aromatic or heterocyclic diacyl, the group —CO— or —CO.CO—, a sulphonyl or sulphonyl residue or a divalent residue obtained by removing two hydroxyl groups from a disulphonic acid, a phosphorus containing acid or a boric acid; when n is 3, R₃ is a trivalent residue of an aliphatic or aromatic triacyl residue or a triacyl residue derived from o-phosphoric, o-phosphorous or o-boric acid; and when n is 4, R₃ is a tetravalent residue of a tetraacyl residue derived from an aliphatic or aromatic tetracarboxylic acid or from o-silicic acid.

C. Compounds of the formula I wherein n is 1 or 2 and when n is 1 R₃ is a carbamoyl residue having the formula:

wherein R₈ is hydrogen or an alkyl residue having from 1 to 4 carbon atoms, and R₉ is hydrogen, an alkyl residue having from 1 to 20 carbon atoms, an alkenyl residue having from 3 to 20 carbon atoms, a cycloalkyl residue having from 5 to 12 carbon atoms or an unsubstituted aryl or substituted aryl residue having from 6 to 12 carbon atoms; and when n is 2 R₃ is a divalent aliphatic or aromatic dicarbamoyl residue.

D. Compounds of the formula I wherein n is 1 or 2 and when n is 1 R₃ is a thiocarbamoyl residue having the formula:

wherein R₈ is hydrogen or an alkyl residue having from 1 to 4 carbon atoms, and R₉ is hydrogen, an alkyl residue having from 1 to 20 carbon atoms, an alkenyl residue having from 3 to 20 carbon atoms, a cycloalkyl residue having from 5 to 12 carbon atoms or an unsubstituted aryl or substituted aryl residue having from 6 to 12 carbon atoms; and when n is 2, R₃ is a divalent aliphatic or aromatic dithiocarbamoyl.

22

E. Compounds of the formula I wherein when n is 1 R₃ is a monovalent residue and is an alkyl residue having from 1 to 20 carbon atoms, a cycloalkyl residue having from 5 to 12 carbon atoms, an alkenyl or alkynyl residue having from 3 to 20 carbon atoms, an aralkyl residue having from 7 to 9 carbon atoms, or a residue having the formula: wherein m is 1, 2 or 3, R₄ is a hydrogen, methyl or phenyl residue, X₂ is halogen, cyano,

10

15 —COR₅, —CO.OR₅, —CO.SR₅ or —CONR₅R₆ and X₁ is hydroxyl, halogen, cyano, —OR₅, —O—CO.R₅, —OCSR₅, —O.CO.NR₅R₆, —CO.R₅, —CO.OR₅, —CO.SR₅, —CO.NR₅R₆ or —CS.NR₅R₆, wherein R₅ is an alkyl residue having from 1 to 20 carbon atoms, an alkenyl residue having from 2 to 20 carbon atoms, a cycloalkyl residue having from 5 to 12 carbon atoms, an aryl residue having from 6 to 11 carbon atoms, or an aralkyl residue having 7 to 11 carbon atoms, or when R₅ is joined to a nitrogen atom, also hydrogen and R₆ is hydrogen or an alkyl residue having from 1 to 4 carbon atoms, or R₅ and R₆ together with the nitrogen atom to which they are bound form a 5- or 6-membered ring which contains no other heteroatoms or contains one or more other heteroatoms or R₃ is an aryl residue or a residue having the formula:

30

40 wherein R₁' is hydrogen or R₁' has the same significance as R₁ of claim 2; when n is 2, R₃ is a divalent residue and is an alkylenyl residue having from 1 to 20 carbon atoms, an alkenylene residue having from 3 to 20 carbon atoms, an alkynylene residue having from 3 to 20 carbon atoms, an arylene residue having 6 to 14 carbon atoms, an aralkylene residue having from 8 to 14 carbon atoms; when n is 3, R₃ is a trivalent residue of an alkanetriyl, an arenetriyl, or arenetriyltrialkylene group; and when n is 4, R₃ is tetravalent residue of an alkanetetrayl group.

F. Compounds of the formula I wherein when n is 1 R₃ is an acyl group

wherein R₇ is an aliphatic or substituted aliphatic residue having from 1 to 20 carbon atoms, an alkenyl or alkynyl residue having from 2 to 20 carbon atoms, a cycloaliphatic residue having from 5 to 12 carbon atoms, an araliphatic residue having from 7 to 14 carbon atoms, an aromatic residue having from 6 to 12 carbon atoms or an heterocyclic residue, with the proviso that only one of R₁ and R₃ can represent an unsaturated acyl group or R₃ represents a monovalent group obtained by removing a hydroxyl group from a sulphinic acid, a sulphonic acid, a phosphorus containing acid or a boric acid, a phosphorus containing acid or a boric acid.

acid, when n is 2, R_3 is a divalent residue of an aliphatic, aromatic or heterocyclic diacyl residue, a carbonyl, sulphonyl or sulphonyl residue or a divalent residue obtained by removing two hydroxyl groups from a disulphonic acid, a phosphorus containing acid or a boric acid; when n is 3, R_3 is a trivalent residue of an aliphatic or aromatic triacyl residue or a triacyl residue derived from o-phosphoric, o-phosphorous or o-boric acid and when n is 4, R_3 is a tetravalent residue of a tetraacyl residue derived from an aliphatic or aromatic tetracarboxylic acid or from o-silicic acid.

【G. Compound of the formula I wherein n is 1 or 2 and when n is 1, R_3 is a carbamoyl residue having the formula:】

【wherein R_8 is hydrogen or an alkyl residue having from 1 to 4 carbon atoms, and R_9 is hydrogen, an alkyl residue having from 1 to 20 carbon atoms, an alkenyl residue having from 3 to 20 carbon atoms, a cycloalkyl residue having from 5 to 12 carbon atoms or an aryl or substituted aryl residue having from 6 to 12 carbon atoms; and when n is 2, R_3 is a divalent residue of an aliphatic or aromatic dicarbamoyl residue.】

【H. Compounds of the formula wherein n is 1 or 2 and when n is 1, R_3 is a thiocarbamoyl residue having the formula:】

【wherein R_8 is hydrogen or an alkyl residue having from 1 to 4 carbon atoms, and R_9 is hydrogen, an alkyl residue having from 1 to 20 carbon atoms, an alkenyl residue having from 3 to 20 carbon atoms, a cycloalkyl residue having from 5 to 12 carbon atoms or an aryl or substituted aryl residue having from 6 to 12 carbon atoms; and when n is 2, R_3 is a divalent residue of an aliphatic or aromatic dithiocarbamoyl residue.】

【I.】 G. Compounds of formula I and their bicarbonate wherein n is 1, 2 or 3 R_1 is alkyl having from 1 to 18 carbon atoms, benzyl or alkenyl having 3 carbon atoms or a group of the formula:

wherein R_4 is hydrogen, methyl or phenyl and X_1 is a group of the formula

and X_2 is a group of the formula

wherein R_3 R_5 is alkyl having 1 or 2 carbon atoms or phenyl or R_1 is a group of the formula

and R_2 is hydrogen and R_3 when n is 1 is alkyl having 3 to 18 carbon atoms, alkenyl having 3 carbon atoms, propargyl, benzyl, $-\text{CH}_2\text{CH}_2\text{CN}$ or a group of the formula $-\text{CH}_2\text{X}$ wherein X_2 is

15 wherein R_7 is alkyl having 1 to 19 carbon atoms, $\text{CH}_3(\text{CH}_2)_{11}-\text{S}-\text{CH}_2-$, cycloalkyl having 6 to 10 carbon atoms, alkenyl having 2 to 17 carbon atoms, unsubstituted aralkyl having 7 to 13 carbon atoms, $\text{C}_6\text{H}_5-\text{CH}=\text{CH}-$, aralkyl substituted by hydroxy or butyl, unsubstituted aryl having 6 to 10 carbon atoms, aryl substituted by alkyl having 1 to 4 carbon atoms, $\text{CH}_3\text{O}-$, Cl, OH or

wherein R_9 is alkyl having 1 to 8 carbon atoms, alkenyl having 3 carbon atoms, cyclohexyl, unsubstituted aryl having 6 to 10 carbon atoms, aryl substituted by methyl or Cl or R_3 when n is 2 is the group $-\text{CO}-\text{R}-\text{CO}-$ wherein R is alkenyl having 4 to 8 carbon atoms, $-\text{CH}_2\text{CH}_2-\text{S}-\text{CH}_2\text{CH}_2-$, vinylen, cyclohexylen, a divalent thiophen residue, unsubstituted phenylen or phenylen substituted by

or a group of the formula $-\text{CONHR}^1\text{NHCO}-$ wherein R^1 is hexylen, unsubstituted arylene having 6 to 10 carbon atoms, arylene substituted by methyl or R^1 is the group

or a group of the formula $-\text{COCO}-$ or butylen or R_3 when n is 3, is

【J.】 H. Compounds of the formula I wherein n is 1, 2 or 4 and when n is 1, R_3 is an acyl group

wherein R_7 is hydrogen, an substituted aliphatic residue having from 1 to 20 carbon atoms, a alkenyl or alkynyl residue having from 2 to 20 carbon atoms, a cycloal-

phatic residue having from 5 to 12 carbon atoms, an araliphatic residue having from 7 to 14 carbon atoms, or an heterocyclic residue, or R_3 represents a monovalent group obtained by removing a hydroxyl group from a sulphinic acid, a sulphonnic acid, a phosphorus containing acid or a boric acid, or when n is 2, R_3 is a divalent residue of heterocyclic diacyl residue or a sulphinyl or sulphonyl residue or a divalent residue obtained by removing two hydroxyl groups from a disulphonic acid, a phosphorus containing acid or a boric acid; or when n is 4, R_3 is a tetraacyl residue derived from an aliphatic tetracarboxylic acid.

【K.】 I. Compounds of the formula I wherein n is 1, 2 and 4 and when n is 1, R_3 is an acyl group

wherein R_7 is hydrogen, a cycloaliphatic residue having from 5 to 12 carbon atoms or a heterocyclic residue or R_3 represents a monovalent group obtained by removing a hydroxyl group from a sulphinic acid, a sulphonnic acid, a phosphorus containing acid or a boric acid or when n is 2, R_3 is a divalent residue of a heterocyclic diacyl or a sulphinyl or sulphonyl residue or a divalent residue obtained by removing two hydroxyl groups from a disulphonic acid, a phosphorus containing acid or when n is 4, R_3 is a tetraacyl residue derived from an aliphatic tetracarboxylic acid.

【L.】 Compounds of the formula I wherein n is 1, 2 or 4 and when n is 1, R_3 is an acyl group】

【wherein R_7 is hydrogen, substituted aliphatic residue having from 1 to 20 carbon atoms, an alkenyl or alkynyl residue having from 2 to 20 carbon atoms, a cycloaliphatic residue having from 5 to 12 carbon atoms, an araliphatic residue having from 7 to 14 carbon atoms, or an heterocyclic residue, or R_3 represents a monovalent group obtained by removing a hydroxyl group from a sulphinic acid, a sulphonnic acid, a phosphorus containing acid or a boric acid or when n is 2, R_3 is a divalent residue of heterocyclic diacyl residue or a sulphinyl or sulphonyl residue or a divalent residue obtained by removing two hydroxyl groups from a disulphonic acid, a phosphorus containing acid or a boric acid; or when n is 4, R_3 is a tetraacyl residue derived from an aliphatic tetracarboxylic acid.】

【M.】 Compounds of the formula I wherein n is 1, 2 and 4 and when n is 1, R_3 is an acyl group】

【wherein R_7 is hydrogen, a cycloaliphatic residue having from 5 to 12 carbon atoms or a heterocyclic residue or R_3 represents a monovalent group obtained by removing a hydroxyl group from a sulphinic acid, a sulphonnic acid, a phosphorus containing acid or a boric acid or when n is 2, R_3 is a divalent residue of a heterocyclic diacyl or a sulphinyl or sulphonyl residue or a divalent residue obtained by removing two hydroxyl groups from a disulphonic acid, a phosphorus containing acid or a boric acid; or when n is 4, R_3 is a tetraacyl residue derived from an aliphatic tetracarboxylic acid.】

ing acid or when n is 4, R_3 is a tetraacyl residue derived from an aliphatic tetracarboxylic acid.】

【N.】 J. Compounds of the formula I wherein when n is 1, R_3 is an acyl group

10 wherein R_7 is an unsubstituted aliphatic residue having from 1 to 20 carbon atoms or an aromatic residue having from 6 to 20 carbon atoms and when n is 2, R_3 is an divalent aliphatic or aromatic diacyl residue or the groups $-\text{CO}-$ or $-\text{COCO}-$ and when n is 3, R_3 is a trivalent residue and is an aliphatic or aromatic triacyl residue or a triacyl residue derived from o-phosphoric, o-phosphorous or o-boric acid and when n is 4, R_3 is a tetravalent residue of a tetraacyl residue derived from an aromatic tetracarboxylic acid or from o-silicic acid.

【O.】 Compounds of the formula I wherein when n is 1, R_3 is an acyl group】

【wherein R_7 is an unsubstituted aliphatic residue having from 1 to 20 carbon atoms or an aromatic residue having from 6 to 12 carbon atoms and when n is 2, R_3 is an divalent aliphatic or aromatic diacyl residue or the carbonyl group and when n is 3, R_3 is a trivalent residue and is an aliphatic or aromatic triacyl residue or a triacyl residue derived from o-phosphoric o-phosphorous or o-boric acid and when n is 4, R_3 is a tetravalent residue of a tetraacyl residue derived from an aromatic tetracarboxylic acid or from o-silicic acid.】

【The following groups P and Q are sub-groups of the compounds of formula Ia.】

【P.】 K. Compounds of the formula Ia wherein n is 1 and R is hydrogen or a monovalent alicyclic residue having from 5 to 12 carbon atoms.

【Q.】 L. Compounds of the formula Ia wherein when n is 1, R is a monovalent aliphatic residue having from 1 to 20 carbon atoms or a monovalent aromatic residue having from 6 to 20 carbon atoms and when n is 2, R is a divalent aliphatic residue having from 1 to 20 carbon atoms or a divalent aromatic residue having from 6 to 20 carbon atoms.

The following compounds of the formula I are also a group of compounds of the present invention.

wherein n is 1, 2, 3 or 4; R_1 is a monovalent residue and is an alkyl residue having from 1 to 20 carbon atoms, a cycloalkyl residue having from 5 to 12 carbon atoms, an alkenyl or alkynyl residue having from 3 to 20 carbon atoms, an aralkyl residue having from 7 to 9 carbon atoms, or a residue having the formula:

wherein m is 1, 2 or 3, R₄ is a hydrogen, methyl or phenyl residue, X₂ is halogen, cyano,

—COR₅, —CO.OR₅, —CO.SR₅, —CONR₅R₆ or —CS.NR₅R₆ and X₁ is hydroxyl, halogen, cyano,

—OR₅, —O—CO.R₅, OCSR₅, —O.CO.NR₅R₆, —CO.R₅, —CO.OR₅, —CO.SR₅, —CO.NR₅R₆, —CS.NR₅R₆, or —SR₅, wherein R₅ is an alkylresidue having from 1 to 20 carbon atoms, an alkenyl residue having from 2 to 20 carbon atoms, a cycloalkyl residue having from 5 to 12 carbon atoms, an aryl residue having from 6 to 11 carbon atoms, or when R₅ is joined to a nitrogen atom, also hydrogen, and R₆ is hydrogen or a nalkyl residue having from 1 to 4 carbon atoms, or R₅ and R₆ together with the nitrogen atom to which they are bound form a 5- or 6-membered ring which contains no other heteroatom or contains one or more other heteroatoms or R₁ is an acyl group, an unsubstituted or N-substituted carbamoyl or thiocarbamoyl group; R₂ is an alkyl residue having from 1 to 4 carbon atoms, an alkenyl or alkynyl residue having 3 to 20, carbon atoms, a cycloalkyl residue having from 5 to 12 carbon atoms, an aryl residue having from 6 to 11 carbon atoms or an aralkyl residue having from 7 to 9 carbon atoms or also hydrogen; and when n is 1, R₃ is a monovalent radical having the same significance as R₁, with the proviso that only one of R₁ and R₃ can represent a unsaturated acyl group or R₃ represents a monovalent group obtained by removing a hydroxyl group from a sulphuric acid, a sulphonic acid, a phosphorus containing acid or a boric acid, or R₃ is an aryl residue or a residue having the formula:

wherein R_1' is hydrogen or R_1' has the same significance as R_1 .

When n is 2, R₃ is a divalent residue and is an alkylene residue having from 1 to 20 carbon atoms, an alkenylene residue having from 3 to 20 carbon atoms, an alkynylene residue having from 3 to 20 carbon atoms, an arylene residue having 6 to 14 carbon atoms, an aralkylene residue having from 8 to 14 carbon atoms or an aliphatic, aromatic or heterocyclic diacyl residue, an aliphatic or aromatic dicarbamoyl or dithiocarbamoyl, a carbonyl, sulphonyl or sulphonyl residue or a divalent residue obtained by removing two hydroxyl groups from a disulphonic acid, a phosphorus containing acid or a boric acid; when n is 3, R₃ is a trivalent residue or an aliphatic or aromatic triacyl residue or a triacyl resi-

due derived from o-phosphoric, o-phosphorous or o-boric acid or an alkanetriyl, an arenetriyl, or arenetriyltrialkylene group; and when n is 4, R_3 is a tetravalent residue and is a tetravalent aliphatic residue or tetraacyl residue derived from an aliphatic or aromatic tetracarboxylic acid or from o-silicic acid or an alkanetetracyl group; as well as partial ethers, esters and carbamoyloxy and thiocarbamoyloxy compounds related to the fully reacted compounds of formula I.

The following compounds of the formula II are also a group of compounds of the present invention [1]:

and their salts, wherein R' and R'' are the same or different and each is a straight or branched alkyl group, having from 1 to 4 carbon atoms, or R' and R'' together with the carbon atom to which they are attached form a cycloalkyl residue having from 5 to 12 carbon atoms; Y is an alkyl group having from 1 to 20 carbon atoms, preferably 1 to 4, carbon atoms, alkenyl having from 2 to 20 carbon atoms or an aralkyl residue having from 7 to 9 carbon atoms and n₁ is 1 or 2; when n is 1, R is hydrogen or a monovalent aliphatic residue having from 1 to 20, preferably 6 to 20 carbon atoms, a monovalent alicyclic residue having from 5 to 12 carbon atoms, or a monovalent aromatic residue having from 6 to 20 carbon atoms; and when n is 2, R is a divalent aliphatic residue having from 1 to 20, preferably [1] 4 to 20, carbon atoms, and is unsubstituted or substituted or interrupted by one or more, preferably one, sulphur atom, a divalent alicyclic residue having from 5 to 12 carbon atoms or a divalent aromatic residue having from 6 to 20 carbon atoms.

Subgroups of the compounds of formula II are

- a. Compounds wherein Y is methyl or
  - b. Compounds wherein n is 1 and R is a monovalent aliphatic, alicyclic or aromatic residue having from 6 to 20 carbon atoms and this group has the formula:

wherein R_{10} and R_{11} are the same or different and each is an alkyl group having from 1 to 6 carbon atoms, A is

or $-\text{CH}_2\text{CH}_2-$ and p is 0 1, or

- c. Compounds wherein R_{10} and R_{11} are methyl, isopropyl or t-butyl groups or

d. Compounds wherein n is 2 and R is a methylene, 1,2-ethylene, 1,4-butylene, 1,8-n-octylene, 2,2,4-trimethyl-1,4-butylene, 1,10-n-decylene, 1,2-eicosylene, vinylene, propenylene, 1,2-, 1,3- or 1,4-cyclohexylene, cyclohexyl-3-ene, 1,2-, 1,3- or 1,4-phenylene, p-xylylene, 1,4- or 1,5-naphthylene, diphenylene or diphenylmethylen residue or the group —CH₂CH₂S CH₂CH₂— or R is absent.

e. Compounds in the form of its salt of an inorganic or organic acid.

f. Compounds wherein the salt is a phosphate, carbonate, sulphate, chloride, acetate, stearate, maleate, nitrate, tartrate, oxalate, benzoate or substituted carbamate.

G. Compounds wherein R' and R'' are methyl.

The following compounds of the formula IV are also compounds of the present invention:

and its salts wherein R^{III} and R^{IV} are the same or different and each is a straight- or branched alkyl residue having from 1 to 12 carbon atoms or R^{III} and R^{IV} together with the carbon atom to which they are each attached form a cycloalkyl group having from 5 to 12 carbon atoms. Y is a straight- or branched alkyl residue having from 1 to 12 carbon atoms, an alkenyl residue having from 3 to 12 carbon atoms or an aralkyl residue having from 7 to 12 carbon atoms and R₁₂ is hydrogen or a saturated or unsaturated hydrocarbyl residue containing up to 20 carbon atoms optionally substituted, [Y] by halogen or alkoxy having from 1 to 4 carbon atoms and q is 1 or 2. Sub-groups of the compounds of formula IV are:

a. Compounds wherein q is 1 and R₁₂ is an aliphatic residue having from 1 to 20 carbon atoms, an alicyclic residue having from 5 to 12 carbon atoms or an aromatic residue having from 6 to 12 carbon atoms.

b. Compounds wherein R₁₂ is a methyl, ethyl, propyl, isopropyl, n-butyl, 2-ethylhexyl, dodecyl, octadecyl, allyl, oleyl cyclohexyl, benzyl, phenyl o-, m- or p-tolyl, 2,4- or 2,6-xylyl or a naphthyl residue.

c. Compounds wherein q is 2 and R₁₂ is an aliphatic residue having from 1 to 20 carbon atoms, an alicyclic residue having from 5 to 15 carbon atoms or an aromatic residue having from 6 to 15 carbon atoms.

d. Compounds wherein R₁₂ is a 1,2-ethylene, 1,6-hexylene, 2,4,4-trimethyl-1,6-hexylene, 1,3- or 1,4-phenylene, 2,4-tolylene, 1,5-naphthylene or 4,4'-diphenylmethylen residue.

e. Compounds wherein Y₁ is methyl.

f. Compounds in the form of its salt of an inorganic or organic acid.

g. Compounds wherein the salt is a phosphate, carbonate, sulphate, chloride, acetate, carbonate, sulphate, chloride, acetate, stearate, maleate, citrate, tertrate, oxalate, benzoate or substituted carbamate.

h. Compounds wherein R^{III} and R^{IV} are methyl.

According to the present invention, there is also provided a first process in which a compound of formula I

is produced, comprising reacting, in the presence of an acidbinding agent, a piperidinol having the formula:

wherein R₁ and R₂ have their previous significance, with an acid halide having the formula:

wherein R₃ and n have their previous significance and hal represents a halogen atom, preferably a chlorine atom.

Suitable acid binding agents are organic bases such as triethylamine; alternatively, an excess amount of the amine V can serve as the acid binding agent.

The reaction is conveniently carried out by heating the reactants together in a solvent such as cyclohexane, benzene or toluene which is inert under the reaction conditions. When the reaction is complete, the desired product is then separated by conventional techniques.

The present invention also provides a second process in which a compound of formula I is produced, comprising reacting, in the presence of a transesterification catalyst, a piperidinol compound of formula V, as hereinbefore defined, with an ester having the formula:

wherein R₃ and n have their previous significance and R₁₃ is an alkyl residue having from 1 to 4 carbon atoms, preferably 1 or 2 carbon atoms.

Examples of suitable transesterification catalysts are alkali metal amides such as lithium amide.

A third process according to this invention in which a compound of formula I is produced comprises reacting, in the presence of an esterification catalyst, a piperidinol compound of formula V, as hereinbefore defined, with an acid having the formula:

wherein R₃ and n have their previous significance.

Suitable examples of esterification catalysts are neutral catalysts such as tetraalkyl titanates such as tetrabutyl titanate.

The second and third processes of the invention are conveniently effected by mixing the reactants together in the presence or absence of an inert solvent (for instance, benzene, toluene, xylene etc.) and agitating the reaction mixture until reaction is complete, as determined, for instance, by collecting the alcohol or water produced in the reaction, and stopping the reaction when the theoretical amount of alcohol or water, respectively, has been removed.

A fourth process in which a compound of formula I is produced comprises reacting a compound having the formula:

wherein R₂, R₃ and n have their previous significance, with a compound X capable of reaction with the compound IX and of introducing into it the group R₁ as hereinbefore defined.

For instance, compound X may be an alkylating, 15 alkenylating or aralkylating agent such as the halides of these groups. Compound X may also be the aldehyde or ketone corresponding to the substituent R₁, so that, when reacted with a compound of formula IX under Leuckart, Wallach or Eschweiler-Charles reaction conditions, compounds of formula I in which R₁ is methyl may be produced by reacting a compound of formula IX with formic acid and formaldehyde.

The starting-materials of formulae V, VI, VII, VIII, 25 IX and X used in the process of this invention can all be produced by methods well-known per se. The compounds of formula V are described in our copending British Patent Application No. (Case 32/72) and those of formula IX are described generally in German Patent Specification No. 1,929,928.

Compounds of the general formula I in which 30 [b]n=2, 3 or 4 and R₃ represents a di-, tri- or tetravalent radical derived from an alkyl, alkenyl, aryl or aralkyl radical may be prepared by reacting a compound of the formula:

R₁ and R₂ has its previous significance, with a compound of the formula R₃(X₄)_n wherein X₄ is a halogen atom and n is 2, 3 or 4. This reaction is preferably carried out by making the sodium salt of the piperidine compound and reacting this with the compound R₃(X₄)_n.

The substituents R₁ may be introduced before or after R₃ or in the case where R₁ and R₃ are identical may be introduced together by reacting a compound of the formula:

with an alkylating, alkenylating, alkynylating, aralkylating, acylating agent or carbamoyloxyating agent, with an alkylating alkenylating, alkynylating, aralkylating or acylating agent.

Compounds of formula I in which R₁ represents a residue of the formula:

in which R₄ is as defined above, m is 1 and X₁ represents -CN, -OR₅,

R₅ and R₆ being as defined above, may be produced by reacting a compound of the formula:

wherein R₃ and R₂ are as defined above, with a compound having the formula

Compounds of formula I wherein m is 1 and X₁ is -OH may be prepared by reacting a compound of formula XII with ethylene oxide, propylene oxide or 40 styrene oxide.

Compounds of formula I wherein R₁ is

or halogen may be prepared from the corresponding compounds wherein X₁ is -OH by standard methods, such as alkylation, esterification, carbamoyloxylation or halogenation.

Compounds of formula I in which R₁ represents a residue of formula:

wherein m, R₄ and X₁ are as hereinbefore defined may be prepared by reacting a compound of formula XII with the appropriate halogen compound having the formula:

wherein X₃ is a halogen atom.

Compounds of formula I in which R₁ is the group of formula:

wherein X₂ and R₄ are as defined above may be prepared by reacting a compound of the formula XII wherein R₂ is as defined above with a compound of the formula

wherein X₄ is a halogen atom.

Compounds of the general formula I in which R₁ represents an acyl group may be prepared by reacting a compound of the formula:

wherein R₂ and R₃ are as defined above with an acyl halide of the formula

wherein X₅ is a halogen, and R₁₄ is the remainder of the acyl group.

Compounds of the general formula I in which R₁ represents a carbamoyl or thiocarbamoyl group may be prepared by reacting a compound of the formula:

R₂ and R₃ being as defined above with an isocyanate or thioisocyanate of the formula R₁₅NCX¹ in which X¹ is

and R₁₅ is the remainder of the isocyanate or thioisocyanate group.

Where R₂ in the general formula I is other than hydrogen it is preferred to introduce the appropriate group before or after the group R₁ is introduced, but

before R₃ is introduced. The group R₂ may be introduced by reacting a ketone of the formula:

wherein R₁¹ is hydrogen R₁, with a Grignard reagent R₂MgX followed by hydrolysis to produce a compound of the formula:

All the reactions described above which result in the elimination of hydrogen halide between two reactants may be carried out in the presence of an acid acceptor.

Compounds of formula II as defined hereinbefore are produced by reacting, in the presence of an acid-binding agent, a piperidinol compound having the formula:

XIV

wherein Y, R' and R'' are as defined hereinbefore with an acid halide having the formula:

wherein R and n are as defined hereinbefore and hal. represents a halogen atom. The acid binding agent can be an organic base of an excess amount of the amine reactant XIV and the reactants are for example heated together in a solvent inert under the reaction conditions.

The process can be performed in the presence of a transesterification catalyst, such as an alkali metal, a piperidinol compound having the formula XIV, with an ester having the formula:

wherein R and n are as defined above and R₁₆ is an alkyl group having from 1 to 4 carbon atoms, or with an acid having the formula:

wherein R and n are as defined above.

The catalyst of producing compounds of the formula II can be a neutral catalyst such as tetraalkyl titanate.

In the process for producing compounds of the formula II the reactants can also be fused, the mass is agitated until reaction is complete and the reaction is stopped when the reaction is complete. The completion

of the reaction is determined for example by collecting, respectively, the alcohol or water produced in the reaction, and stopping the reaction when the theoretical amount of water or alcohol has been removed.

Compounds of formula II are also produced by reacting an ester having the formula:

wherein R, R', R'' and n are as defined above with a compound capable of reacting with the ester XV such as an alkylating or aralkylating agent or an aldehyde or ketone corresponding to the substituent Y and of introducing into it the group Y as defined above.

Compounds having the formula IV as defined hereinbefore are produced by reacting a compound having the formula:

wherein Y, R'' and R''' are as defined hereinbefore with an isocyanate having the formula:

wherein R₁₂ and q are as defined hereinbefore. The reaction can be effected in a solvent inert under the reaction conditions and in the presence of a strong base.

The present invention still further provides a composition comprising an organic material and a stabilising amount of a compound having the formula I, II or IV as hereinbefore defined.

Compounds of formula I, II exceptionally IV, have been found to impart to polyolefines an exceptionally high degree of stability towards deterioration normally induced by the effects of ultra-violet radiation or exposure to heat. Moreover, this improved stability is achieved without affecting the colour properties of the treated polyolefine. The stabilisers of the invention provide effective light and/or heat stabilisation, especially for low- and high-density polyethylene and polypropylene and polystyrene as well as polymers of butene-1, pentene-1, 3-methyl-butene-1, hexane-1, 4-methylpentene-1, 4-methylhexene-1 and 4,4-dimethylpentene-1, and also co- and ter-polymers of olefines, particularly of ethylene or propylene.

Other organic materials susceptible to degradation by the effects of light and the properties of which are improved by the incorporation therein of a compound of formula I, II or IV, include natural and synthetic polymeric materials, for instance natural and synthetic rubbers, the latter including, for example, homo-, co- and ter-polymers of acrylonitrile, butadiene and styrene.

Specific synthetic polymers include polyvinyl chloride, polyvinylidene chloride and vinyl chloride co-

polymers polyvinyl acetate as well as condensation polymers derived from ether, ester (derived from carboxylic sulphonic or carbonic acids), amide or urethane groupings. These polymers can, for instance, form the basis of surface coating media such as paints and lacquers having an oil or resin, for instance an alkyd or polyamide resin base.

The amount of the compound of formula I, II or IV, which is incorporated into the organic material in order to achieve maximal protection against degradation by light varies according to the properties of the organic material treated and according to the severity of the light radiation and to the length of exposure. However, for most purposes it is sufficient to use an amount of the compound of formula I, II or IV, within the range of from 0.01% to 5% by weight, more preferably within the range of from 0.1% to 2% by weight based on the weight of untreated organic material.

The compounds may be incorporated into the polymeric material by any of the known techniques for compounding additives with a polymer. For example, the compound and the polymer may be compounded in an internal mixer. Alternatively, the compound may be added as a solution or slurry in a suitable solvent or dispersant, for instance an inert organic solvent such as methanol, ethanol or acetone to powdered polymer and the whole mixed intimately in a mixer, and the solvent subsequently removed. As a further alternative the compound may be added to the polymer during the preparation of the latter, for instance at the latex stage of polymer production, to provide pre-stabilised polymer material.

Optionally, the composition of the invention may contain one or more further additives, especially those used in polymer formulations, such as antioxidants of the phenol or amine type, U.V. absorbers and light protectants, phosphite stabilisers, peroxide decomposers, polyamide stabilisers, basic co-stabilisers, polyvinyl chloride stabilisers, nucleation agents, plasticizers, lubricants, emulsifiers, anti-static agents, flame-protectants, pigments, carbon black, asbestos, glass fibres, kaolin and talc.

The present invention therefore includes binary, tertiary and multi-component compositions containing the stabiliser of formula I, II or IV, together with one or more functional additives for polymers.

Examples of suitable antioxidants are those of the hindered phenol type such as those selected from the following groups: 1. Phenolic compounds having the general formula

wherein Q is

A₁ is $-CR(COOR'')_2$

R is hydrogen or lower alkyl,
 R' is lower alkyl,
 R'' is alkyl group having from 6-24 carbon atoms w is
 an integer from 0 to 4.
 Illustrative examples of the compounds shown above
 are:
 di-n-octadecyl- α -(3,5-di-t-butyl-4-hydroxy-benzyl)ma-
 lonate
 di-n-octadecyl- α -(3-t-butyl-4-hydroxy-5-methylben-
 zyl)malonate which is disclosed in the Netherlands
 Pat. No. 6,711,199, Feb. 19, 1968
 di-n-octadecyl- α , α '-bis-(3-t-butyl-4-hydroxy-5-methyl-
 benzyl)malonate which is disclosed in the Nether-
 lands Pat. No. 6,803,498, Sept. 18, 1968.
 2. Phenolic compounds having the general formula

Illustrative examples of the compounds shown above
 are:
 2,6-di-t-butyl-p-cresol
 2-methyl-4,6-di-t-butylphenol and the like
 2,6-di-Octadecyl-p-cresol

3. Phenolic compounds having the formula

Illustrative examples of the compounds shown are:
 2,2'-methylene-bis(6-t-butyl-4-methylphenol)
 2,2'-methylene-bis(6-t-butyl-4-ethylphenol)
 4,4'-butyldene-bis(2,6-di-t-butylphenol)
 4,4'-(2-butyldene)-bis(2-t-butyl-5-methylphenol)
 2,2'-methylene-bis[6-(2-t-methylcyclohexyl)]-4-methyl-
 phenol
 2,2'-methylene-bis(3-t-butyl-5-ethylphenol)
 4,4'-methylene-bis(3,5-di-t-butylphenol)
 4,4'-methylene-bis(3-t-butyl-5-methylphenol)
 2,2'-methylene-bis(3-t-butyl-5-methylphenol) and the
 like.

4. Phenolic compounds having the formula:

Illustrative examples of such compounds are:
 2,5-di-t-butylhydroquinone
 2,6-di-t-butylhydroquinone
 2,5-di-t-butyl-4-hydroxyanisole

5. Phenolic compounds having the formula:

Illustrative examples of such compounds are:
 4,4'-thiobis-(2-t-butyl-5-methylphenol)
 4,4'-thiobis-(2-t-butyl-6-methylphenol)
 2,2'-thiobis-(6-t-butyl-4-methylphenol)
 4,4'-thiobis-(2-methyl-5-t-butylphenol)

6. Phenolic compounds having the formula

Illustrative examples of such compounds are:

5
 38
 octadecyl-(3,5-dimethyl-4-hydroxybenzylthio)-acetate
 dodecyl-(3,5-di-t-butyl-4-hydroxybenzylthio)-propion-
 ate
 7. Phenolic compounds having the formula

wherein T is hydrogen
 R or Q as defined above.

Illustrative examples of such compounds are:
 15 1,1,3-tris(3,5-dimethyl-4-hydroxyphenyl)-propane
 1,1,3-tris(5-t-butyl-4-hydroxy-2-methylphenyl)-butane
 1,1,5,5-tetrakis-(3'-t-butyl-4'-hydroxy-6'-methylphenyl)-
 n-pentane
 8. Phenolic compounds having the formula:

30 wherein B¹, B² and B³ are hydrogen, methyl or Q, pro-
 vided that when B¹ and B³ are Q then B² is hydrogen or
 methyl and when B² is Q then B¹ and B³ are hydrogen
 or methyl.

Illustrative examples of such compounds are:
 35 1,4-di(3,5-di-t-butyl-4-hydroxybenzyl)-2,3,5,6-tetrameth-
 ylbenzene
 1,3,5-tri(3,5-di-t-butyl-4-hydroxybenzyl)-2,4,6-trimeth-
 ylbenzene
 40 8. 9. Phenolic compounds having the formula

50 wherein Z is NHQ, —S—D— or —O—Q D is alkyl
 group having from 6-12 carbon atoms or —(C_wH_{2w}—)
 —S—R"

Illustrative examples of such compounds are:
 2,4-bis-(o-octylthio)-6-(3,5-di-t-butyl-4-hydroxyaniline)-
 1,3,5-triazine
 55 6-(4-hydroxy-3-methyl-5-t-butylanilino)-2,4-bis-(n-
 octylthio)-1,3,5-triazine
 6-(4-hydroxy-3,5-dimethylanilino)-2,4-bis-(n-octylthio)-
 1,3,5-triazine
 6-(4-hydroxy-3,5-di-t-butylanilino)-2,4-bis-(n-octylthi-
 o)-1,3,5-triazine
 60 6-(4-hydroxy-3,5-di-t-butylanilino)-4-(4-hydroxy-3,5-di-
 t-butylphenoxy)-2-(n-octylthio)-1,3,5-triazine
 2,4-bis(4-hydroxy-3,5-di-t-butylanilino)-6-(n-octylthio)-
 1,3,5-triazine
 65 The above phenolic triazine stabilizers are more fully
 described in U.S. Pat. No. 3,255,191. 10. Phenolic com-
 pounds having the formula:

wherein Z' is $-\text{O}-\text{Q}$, $-\text{S}-\text{D}$ or $-\text{S}-(\text{C}_\omega\text{H}_{2\omega})-\text{SD}$.

Illustrative examples of such compounds are:

- 2,3-bis-(3,5-di-t-butyl-4-hydroxyphenoxy)-6-(n-octylthio)-1,3,5-triazine
 2,4,6-tris-(4-hydroxy-3,5-di-t-butylphenoxy)-1,3,5-triazine
 6-(4-hydroxy-3,5-di-t-butylphenoxy)-2,4-bis-(n-octylthio)-1,3,5-triazine
 6-(4-hydroxy-3-methylphenoxy)-2,4-bis-(n-octylthio)-1,3,5-triazine
 6-(4-hydroxy-3-t-butylphenoxy)-2,4-bis-(n-octylthioethylthio)-1,3,5-triazine
 6-(4-hydroxy-3-methyl-5-t-butylphenoxy)-2,4-bis-(n-octylthio)-1,3,5-triazine
 2,4-bis-(4-hydroxy-3-methyl-5-t-butylphenoxy)-6-(n-octylthio)-1,3,5-triazine
 2,4,6-tris(4-hydroxy-3-methyl-5-t-butylphenoxy)-1,3,5-triazine
 6-(4-hydroxy-3,5-di-t-butylphenoxy)-2,4-bis-(n-octylthiopropylthio)-1,3,5-triazine
 6-(4-hydroxy-3,5-di-t-butylphenoxy)-2,4-bis-(n-dodecylthioethylthio)-1,3,5-triazine
 2,4-bis-(4-hydroxy-3,5-di-t-butylphenoxy)-6-butylthio-1,3,5-triazine
 2,4-bis-(4-hydroxy-3,5-di-t-butylphenoxy)-6-(n-octadecylthio)-1,3,5-triazine
 2,4-bis-(4-hydroxy-3,5-di-t-butylphenoxy)-6-(n-dodecylthio)-1,3,5-triazine
 2,4-bis-(4-hydroxy-3,5-di-t-butylphenoxy)-6-(n-octylthiopropylthio)-1,3,5-triazine
 2,4-bis-(4-hydroxy-3,5-di-t-butylphenoxy)-6-(n-octylthioethylthio)-1,3,5-triazine
 2,4-bis-(4-hydroxy-3,5-di-t-butylphenoxy)-6-(n-dodecylthioethylthio)-1,3,5-triazine.

The above phenolic triazine stabilizers are more fully described in U.S. Pat. No. 3,255,191.

11. Phenolic compounds having the formula

wherein p is an integer from 2 to 4 and R''' is a tetravalent radical selected from aliphatic hydrocarbons having from 1 to 30 carbon atoms, aliphatic mono- and di-thioethers having from 1 to 30 carbon atoms, aliphatic mono- and diethers having from 1 to 30 carbon atoms and z is an integer from 0 to 6.

Illustrative examples of such compounds are

Sub-class I

- [n-Octadecyl-]** *n-octadecyl-3-(3,5-di-t-butyl-4-hydroxyphenyl)-propionate*
[n-Octadecyl-] *n-octadecyl-2-(3,5-di-t-butyl-4-hydroxyphenyl)-acetate*
[n-Octadecyl-] *n-octadecyl-3,5-di-t-butyl-4-hydroxybenzoate*
[n-Hexyl-] *n-hexyl-3,5-di-t-butyl-4-hydroxyphenylbenzoate*
[n-Dodecyl-] *n-dodecyl-3,5-di-t-butyl-4-hydroxyphenylbenzoate*

- Neo-dodecyl-3-(3,5-di-t-butyl-4-hydroxyphenyl)-propionate
 Dodecyl- β -(3,5-di-t-butyl-4-hydroxyphenyl)-propionate
 5 Ethyl- α -(4-hydroxy-3,5-di-t-butylphenyl)-isobutyrate
 Octadecyl- α -(4-hydroxy-3,5-di-t-butylphenyl)-isobutyrate
 Octadecyl- α -(4-hydroxy-3,5-di-t-butylphenyl)-propionate

Sub-Class II

- 2-(n-octylthio)ethyl 3,5-di-t-butyl-4-hydroxybenzoate
 2-(n-octylthio)ethyl 3,5-di-t-butyl-4-hydroxyphenylacetate
 10 2-(n-octadecylthio)ethyl 3,5-di-t-butyl-4-hydroxyphenylacetate
 2-(n-octadecylthio)ethyl 3,5-di-t-butyl-4-hydroxybenzoate
 2-(2-hydroxyethylthio)ethyl 3,5-di-t-butyl-4-hydroxybenzoate
 2,2'-**[Thiodiethanol]** *thiodiethanol* bis(3,5-di-t-butyl-4-hydroxyphenyl)acetate
[Diethyl] *diethyl* glycol bis-[3,5-di-t-butyl-4-hydroxyphenyl]propionate
 15 2-(n-octadecylthio)ethyl 3-(3,5-di-t-butyl-4-hydroxyphenyl)propionate
 2,2'-**[Thiodiethanol]** *thiodiethanol* -bis-3-(3,5-di-t-butyl-4-hydroxyphenyl)propionate
[Stearamido] *stearamido* N,N-bis-[ethylene 3-(3,5-di-t-butyl-4-hydroxyphenyl)propionate]
[n-Butylimino] *n-butylimino* N,N-bis-[ethylene 3-(3,5-di-t-butyl-4-hydroxyphenyl)propionate]
 20 2-(2-stearoyloxyethylthio)ethyl 3,5-di-t-butyl-4-hydroxybenzoate
 2,2'-**[Thiodiethanol]** *thiodiethanol* -bis-3-(3,5-di-t-butyl-4-hydroxyphenyl)propionate
[Stearamido] *stearamido* N,N-bis-[ethylene 3-(3,5-di-t-butyl-4-hydroxyphenyl)propionate]
[n-Butylimino] *n-butylimino* N,N-bis-[ethylene 3-(3,5-di-t-butyl-4-hydroxyphenyl)propionate]
 25 2-(2-stearoyloxyethylthio)ethyl 3,5-di-t-butyl-4-hydroxybenzoate
 2,2'-**[Thiodiethanol]** *thiodiethanol* -bis-3-(3,5-di-t-butyl-4-hydroxyphenyl)propionate
[Stearamido] *stearamido* N,N-bis-[ethylene 3-(3,5-di-t-butyl-4-hydroxyphenyl)propionate]
[n-Butylimino] *n-butylimino* N,N-bis-[ethylene 3-(3,5-di-t-butyl-4-hydroxyphenyl)propionate]
 30 2-(2-stearoyloxyethylthio)ethyl 3,5-di-t-butyl-4-hydroxybenzoate
 2,2'-**[Thiodiethanol]** *thiodiethanol* -bis-3-(3,5-di-t-butyl-4-hydroxyphenyl)propionate
[Stearamido] *stearamido* N,N-bis-[ethylene 3-(3,5-di-t-butyl-4-hydroxyphenyl)propionate]
[n-Butylimino] *n-butylimino* N,N-bis-[ethylene 3-(3,5-di-t-butyl-4-hydroxyphenyl)propionate]
 35 2-(2-stearoyloxyethylthio)ethyl 3,5-di-t-butyl-4-hydroxybenzoate
 2-(2-stearoyloxyethylthio)ethyl 7-(3-methyl-5-t-butyl-4-hydroxyphenyl)heptanoate
 2-(2-stearoyloxyethylthio)ethyl 7-(3-methyl-5-t-butyl-4-hydroxyphenyl)heptanoate

Sub-class III

- 1,2-propylene glycol bis-[3-(3,5-di-t-butyl-4-hydroxyphenyl)propionate]
[Ethylene] *ethylene* glycol bis-[3-(3,5-di-t-butyl-4-hydroxyphenyl)propionate]
 40 **[Neopentylglycol]** *neopentylglycol* bis-[3-(3,5-di-t-butyl-4-hydroxyphenyl)propionate]
[Ethylene] *ethylene* glycol bis-(3,5-di-t-butyl-4-hydroxyphenylacetate)
[Glycerine] *glycerine*-1-n-octadecanoate-2,3-bis-(3,5-di-t-butyl-4-hydroxyphenylacetate)
[Pentaethylthritol] *pentaethylthritol*-tetrakis-[3-(3,5-di-t-butyl-4-hydroxyphenyl)propionate]
 45 1,1,1-trimethylol ethane-tris-3-(3,5-di-t-butyl-4-hydroxyphenyl)propionate
[Sorbitol] *sorbitol* hexa-[3-(3,5-di-t-butyl-4-hydroxyphenyl)propionate
 1,2,3-butanetriol tris-[3-(3,5-di-t-butyl-4-hydroxyphenyl)propionate]
 50 2-hydroxyethyl 7-(3-methyl-5-t-butyl-4-hydroxyphenyl)heptanoate
 2-stearoyloxyethyl 7-(3-methyl-5-t-butyl-4-hydroxyphenyl)heptanoate
 1,6-n-hexanediol-bis[3',5'-di-t-butyl-4-hydroxyphenyl]propionate
 55 The above phenolic ester stabilizers of sub-classes I, II and III are more fully described in U.S. Pat. No. 3,330,859, Ser. No. 354,464, filed Mar. 24, 1964 and Ser. No. 359,460, filed Apr. 13, 1964, respectively.

dicyandiamide, urea derivatives, hydrazine derivatives, amines, polyamides, polyurethanes, alkali and alkaline earth salts of higher saturated or unsaturated fatty acids such as calcium stearate.

Polyvinyl chloride stabilisers include organotin compounds, organo lead compounds and Ba/Cd salts of fatty acids.

Examples of nucleation agents are 4-tert.butyl benzoic acid, adipic acid and diphenylacetic acid.

As with the compound of formula I, II or IV any further additive is advantageously employed in a proportion within the range of from 0.01% to 5% by weight, based on the weight of untreated polymeric material.

In binary combinations with one or more antioxidants listed above or in tertiary combinations with such antioxidants and U.V. absorbers listed above, the compounds of formula I, II or IV provide very effective stabiliser packages in polyolefine formulations.

Some Examples will now be given. Parts and percentages are by weight unless otherwise stated.

EXAMPLE 1

A mixture of 10.26 parts of 1,2,2,6,6-pentamethylpiperidin-4-ol, 6.06 parts of sebacic acid and 1.0 parts of

15

10

20

25

tetra-n-butyl titanate in 100 parts of xylene was heated under reflux conditions for 60 hours. Removal of the xylene by distillation under reduced pressure gave an oily solid which was heated under reflux conditions with 0.5 parts of sodium carbonate and 0.5 parts of carbon in 25 parts of water for 1 hour.

Removal of the water by distillation under reduced pressure gave a black residue which was repeatedly extracted with ether. The combined ether extracts were dried and the ether removed by distillation under reduced pressure to give a yellow oil which was distilled under reduced pressure to give 5.0 parts of bis(1,2,2,6,6-pentamethyl-4-piperidinyl) sebacate as a colourless oil having a boiling point of 220°-2° C. at 0.2 mm of Hg and the following elemental analysis by weight:

	Found	Required	(for C ₃₀ H ₅₆ N ₂ O ₄)
Carbon	70.60%	70.82%	
Hydrogen	11.00%	11.10%	
Nitrogen	4.81%	5.51%	

Table I gives a list of esters prepared using the procedure of Example 1.

Purified by
chromatography## EXAMPLE 34

A solution of 17.10 parts of 1,2,2,6,6-pentamethylpiperidin-4-ol in 50 parts of dry benzene was stirred at 15°-20° C. whilst adding 6.0 parts of sebacoyl chloride dropwise over 15 minutes. The mixture was stirred for a further 12 hours at room temperature after which the 1,2,2,6,6-pentamethylpiperidin-4-ol hydrochloride formed during the reaction was filtered off. The benzene was removed by distillation under reduced pressure to give a yellow oil, which was distilled under reduced pressure to give bis-(1,2,2,6,6-pentamethyl-4-piperidinyl)sebacate as a colourless oil having a boiling point of 218°-20° C. at 0.4 mm of Hg and the following elemental analysis by weight:

	Found	Required	(for C ₃₀ H ₅₆ N ₂ O ₄)

EXAMPLE 41

A mixture of 17.10 parts of 1,2,2,6,6-pentamethylpiperidin-4-ol, 13.60 parts of methyl benzoate and 2.0 parts of lithium amide was heated at 160° C. for six hours with removal of the methyl alcohol formed by

distillation. Water pump vacuum was applied and heating continued for a further two hours; on cooling the residue was dissolved in chloroform and filtered to remove the lithium amide. The chloroform was removed by distillation under reduced pressure to give a yellow oil which was fractionally distilled under reduced pressure to yield 6.40 parts of 1,2,2,6,6-pentamethylpiperidin-4-benzoate having a boiling point of 126° C. at 0.1 mm of Hg. and the following elemental analysis by weight:

	Found	Required	(for C ₁₇ H ₂₅ NO ₂)
Carbon	74.35%	74.14%	
Hydrogen	9.23%	9.15%	
Nitrogen	5.13%	5.09%	

EXAMPLE 42

A mixture of 17.10 parts of 1,2,2,6,6-pentamethylpiperidin-4-ol, 14.60 parts of methyl-β-(3,5-di-t-butyl-4-hydroxyphenyl) propionate and 1.0 part of lithium amide was heated together to 130° C. Water pump vacuum was then applied to the reaction mixture whilst

maintaining the temperature at 125°-135° C. for 3 hours.

The temperature of the reaction mixture was then raised to 160° C. and high vacuum (0.5-1 mm Hg) was applied for 1 hour. The reaction mixture was cooled,

dissolved in chloroform and filtered. Removal of the chloroform by distillation under reduced pressure gave a brown oil which, when triturated with ether, gave a white solid which was collected by filtration, washed well with ether and dried to give 16.0 parts of 1,2,2,6,6-pentamethylpiperidinyl-4- β -(3',5'-di-t-butyl-4'-hydroxyphenyl)propionate as its bicarbonate salt having a melting point of 210°-11° C., and the following elemental analysis by weight:

	Found	Required	(for C ₂₈ H ₄₇ NO ₆)
Carbon	68.90%	68.10%	
Hydrogen	9.56%	9.60%	
Nitrogen	2.91%	2.84%	

EXAMPLE 43

15.0 parts of the product from Example 2 were dissolved in water and neutralised with sodium hydroxide solution. The aqueous solution was extracted with ether, the combined ether extracts were dried over anhydrous magnesium sulphate. The ether was removed by distillation under reduced pressure to give a white solid which was recrystallised from ethanol to give 9.30 parts of 1,2,2,6,6-pentamethylpiperidinyl-4- β -(3',5'-di-t-butyl-4'-hydroxyphenyl) propionate having a melting point of 124°-5° C. and the following elemental analysis by weight:

	Found	Calculated	(for C ₂₇ H ₄₅ NO ₃)
Carbon	75.00	75.30	
Hydrogen	10.50	10.20	
Nitrogen	3.50	3.30	

EXAMPLE 44

A mixture of 10.26 parts of 1,2,2,6,6-pentamethylpiperidin-4-ol, 5.04 parts of trimethyl, trimesate and 0.20 parts of lithium amide in 100 parts of xylene was heated at 137° C. for 7 hours. The methyl alcohol formed dur-

ing the reaction being removed by distillation. The cooled reaction mixture was filtered to remove the lithium amide and the xylene solvent removed by distillation under reduced pressure. Purification of the residue by preparative thin layer chromatography yielded dimethyl(1,2,2,6,6-pentamethylpiperidinyl-4) trimesate having the following molecular weight:

10	Found (from mass spectrometry)	391
	Required (for C ₂₁ H ₂₉ NO ₆)	391

and methylbis(1,2,2,6,6-pentamethylpiperidinyl-4) trimesate having the following molecular weight:

15	Found (from mass spectrometry)	530
	Required (for C ₃₀ H ₄₆ N ₂ O ₆)	530.

EXAMPLE 45

A mixture of 16.4 parts of 1,2,2,6,6-pentamethylpiperidin-4-ol, 6.27 parts of methyl isocyanate and 0.5 parts of 1,4-diazabicyclo[2.2.2]octane was refluxed in 150 parts of dry benzene for 24 hours. Removal of the benzene solvent by distillation under reduced pressure yielded an oily solid which was poured on to 200 parts of water and allowed to stand for 24 hours. The solid formed was collected by filtration, dried and crystallised from n-hexane to give 14.2 parts of 4-methylcarbamoyloxy-1,2,2,6,6-pentamethylpiperidine having a melting point of 96°-7° C. and the following elemental analysis by weight:

Table 3 gives a list of carbamoyloxy esters prepared using the procedure of Example 45.

	Found	Required	(for C ₁₂ H ₂₄ N ₂ O ₂)

EXAMPLE 62

A mixture of 28.3 parts of 2,2,6,6-tetramethyl-4-piperidinyl-n-octanoate and 8.55 parts of benzyl bromide was stirred and heated at 105° C. for 72 hours. Ether was added to the cooled reaction mixture and the 2,2,6,6-tetramethyl-4-piperidinyl-n-octanoate hydrobromide formed during the reaction was filtered off. The ether solvent was removed by distillation under reduced pressure and the residue distilled under reduced pressure to give 16.40 parts of 1-benzyl-2,2,6,6-tetramethyl-4-piperidinyl-n-octanoate having a boiling

point of 180° C. at 0.1 mm of Hg and the following elemental analysis by weight:

	Found	Required (for C ₂₄ H ₂₉ NO ₂)
Carbon	77.46%	77.16%
Hydrogen	10.50%	10.52%
Nitrogen	3.86%	3.75%

Table 4 gives a list of esters prepared using the procedure of Example 62.

EXAMPLE 70

A mixture of 17.10 parts of 1,2,2,6,6-pentamethyl-40
piperidin-4-ol and 3.50 parts of metallic sodium in 125
parts of toluene was heated under reflux conditions for
24 hours. The toluene solution was decanted off from
the excess sodium and then refluxed for a further 24
hours with 36.60 parts of n-octadecyl bromide. The 45
cooled solution was filtered to remove the sodium bro-
mide which was formed during the reaction and the
toluene solvent was removed by distillation under re-
duced pressure. Fractional distillation of the residue
gave 4-octadecyloxy-1,2,2,6,6-pentamethylpiperidine

having a boiling point of 184° C. at 0.25 m.m. of Hg. and
the following elemental analysis by weight:

	Found	Required (for C ₂₈ H ₅₇ NO)
Carbon	78.66%	79.36%
Hydrogen	13.77%	13.56%
Nitrogen	2.99%	3.31%

Table 5 gives a list of ethers prepared using the pro-
cedure of Example 70.

EXAMPLE 77

3.23 Parts of 1-allyl-2,2,6,6-tetramethyl-4-piperidinyl-n-octanoate in 50 parts of ethyl alcohol was hydrogenated at room temperature and 1 atmosphere pressure using 0.1 parts of 5% palladium on charcoal at the catalyst. The reaction mixture was filtered to remove the catalyst and the ethyl alcohol removed by distillation under reduced pressure to give 2.90 parts of 1-n-propyl-2,2,6,6-tetramethyl-4-piperidinyl-n-octanoate having a 10 boiling point of 128° C. at 0.05 mm of Hg and the following elemental analysis by weight:

	Found	Required (for C ₂₀ H ₃₉ NO ₂)	15
Carbon	73.50%	73.79%	
Hydrogen	12.26%	12.08%	
Nitrogen	4.31%	4.30%	

Table 6 gives a list of compounds prepared using the 20 procedure of Example 77.

EXAMPLE 80

a. A mixture of 2.83 parts of 2,2,6,6-pentamethyl-4-piperidinyl-n-octanoate and 1.50 parts by volume of liquid ethylene oxide was charged into a 50 ml autoclave previously cooled to -50° C. A pressure of 100 atmospheres of nitrogen was applied and the autoclave heated at 200° C., with stirring, for three hours. Fractional distillation of the cooled reaction mixture yielded 2.30 parts of 1-(2'-hydroxyethyl)-2,2,6,6-tetramethyl-4-piperidinyl-n-octanoate having a boiling point of 186°-7° C. at 0.25 mm of Hg and the following elemental analysis by weight:

	Found	Required (for C ₁₉ H ₃₇ NO ₃)	45
Carbon	69.93%	69.68%	
Hydrogen	11.09%	11.39%	
Nitrogen	4.37%	4.28%	

b. A mixture of 11.32 parts of 2,2,6,6-tetramethyl-4-piperidinyl-n-octanoate and 2.50 parts of 2-bromoethanol was stirred at 100° C. for 65 hours. Petroleum ether (bp 40°-60° C.) was added to the cooled reaction mixture of the 2,2,6,6-tetramethylpiperidinyl-4-n-octanoate hydrobromide formed during the reaction was filtered off. The petroleum ether solvent was removed by distillation under reduced pressure and the residue distilled to yield 1-(2'-hydroxyethyl)-2,2,6,6-tetramethyl-4-piperidinyl-n-octanoate having a boiling point of 176° C. at 0.2 mm of Hg. This sample was identical to that prepared under Example 80a.

EXAMPLE 81

A mixture of 11.45 parts of 4-phenylcarbamoyloxy-2,2,6,6-tetramethylpiperidine and 60 parts of styrene [oxide] oxide in 60 parts of n-hexanol was heated under reflux conditions for 18 hours. The n-hexanol

65

solvent and unreacted styrene oxide were removed by distillation under reduced pressure to yield a pale yellow crystalline solid. Purification by trituration with hot petroleum ether (b.p. 60°-80° C.) yielded 4-phenylcarbamoyloxy-1-[2'-hydroxy-2'-phenylethyl]-2,2,6,6-tetramethylpiperidine having a melting point of 186°-7° C. with the following elemental analysis by weight:

	Found	Required (for C ₂₄ H ₃₂ N ₂ O ₃)
Carbon	72.51%	72.70%
Hydrogen	7.92%	8.13%
Nitrogen	6.91%	7.06%

EXAMPLE 82

A mixture of 5.61 parts of 2,2,6,6-tetramethyl-4-piperidin-n-octanoate and 5.0 parts of propylene oxide were charged to an autoclave. A pressure of 100 atmospheres nitrogen was applied. The mixture was heated

at 200° C. for 3 hours. Fractionation under reduced pressure gave a main fraction b.p. 160°-183° C. at 0.1 mm. which after passing down an alumina type II column eluting with chloroform yielded a pale yellow semi-solid 1-(2'-hydroxypropyl)-2,2,6,6-tetramethyl-4-piperidin-n-octanoate having the following elemental analysis by weight:

	Found	Required (for C ₂₀ H ₃₉ NO ₃)
Carbon	70.20%	70.34%
Hydrogen	11.45%	11.51%
Nitrogen	3.89%	4.10%

EXAMPLE 83

A mixture of 3.27 parts of the product from 80 a., 0.60 parts of acetic acid and 0.1 parts of tetra-n-butyl titanate in 40 parts of xylene was heated under reflux conditions for 24 hours. The xylene solvent was removed by distillation under reduced pressure and the residue fractionally distilled to give 1-(2'-acetoxyethyl)-2,2,6,6-tetramethyl-4-piperidinyl-n-octanoate having a boiling point of 190°-2° C. at 1 m.m. Hg and the following elemental analysis by weight:

	Found	Required (for C ₂₁ H ₃₉ NO ₄)
Carbon	68.17%	68.25%
Hydrogen	10.65%	10.64%
Nitrogen	3.36%	3.79%

EXAMPLE 84

A mixture of 3.27 parts of the product from Example 78 A., 0.63 parts of methyl isocyanate and 0.1 parts of 1,4-diazabicyclo[2.2.2] octane in 30 parts of dry

benzene was heated under reflux conditions for 24 hours. The benzene solvent was removed by distillation under reduced pressure and the residue crystallised from aqueous ethyl alcohol to give 1-(2'-methylcarbonyloxyethyl)-2,2,6,6-tetramethyl-4-piperidinyl-n-octanoate having a melting point of 61°-3° C. and the following elemental analysis by weight:

	Found	Required (for C ₂₁ H ₄₀ N ₂ O ₄)
Carbon	65.72%	65.59%
Hydrogen	10.37%	10.48%
Nitrogen	7.11%	7.28%

EXAMPLE 85

A mixture of 3.0 parts of the products from Example 81, 0.90 parts of phenyl isocyanate and 0.1 parts of 1,4-diazabicyclo[2.2.2]octane in 25 parts of dry benzene was heated under reflux conditions for 24 hours. The benzene solvent was removed by distillation under reduced pressure and the residue crystallised from petroleum ether (b.p. 60°-80° C.) to give 4-phenylcarbamoyloxy-1-[2'-(phenylcarbamoyloxy)-2'-phenylethyl]-2,2,6,6-tetramethylpiperidine having a melting point of 173° C. and the following elemental analysis by weight:

	Found	Required (for C ₃₁ H ₃₇ N ₃ O ₄)
Carbon	72.65%	72.21%
Hydrogen	7.22%	7.23%
Nitrogen	7.97%	8.15%

EXAMPLE 86

A mixture of 3.14 parts of 2,2,6,6-tetramethylpiperidin-4-ol and 3.50 parts of acetic anhydride was heated on a steam bath for one hour. After this time 20 parts of water were added and heating continued for a further one hour. The solution was carefully neutralised with a saturated solution of sodium bi-carbonate and then ether extracted. The combined ether extracts were washed twice with 5% sodium bi-carbonate solution and twice with brine, the ether solution was then dried over anhydrous magnesium sulphate and the ether removed by distillation under reduced pressure to yield 1-acetyl-2,2,6,6-tetramethylpiperidinyl-4-acetate having a melting point of 33°-4° C. and the following elemental analysis by weight:

	Found	Required (for C ₁₃ H ₂₃ NO ₃)
Carbon	64.51%	64.73%
Hydrogen	9.69%	9.54%
Nitrogen	5.67%	5.81%

EXAMPLE 87

A mixture of 15.70 parts of 2,2,6,6-tetramethylpiperidin-4-ol, 22.80 parts of methyl isocyanate and 0.5 parts of 1,4-diazabicyclo[2.2.2]octane in 100 parts of dry benzene was heated under reflux conditions for 24 hours. The benzene solvent was removed by distillation under reduced pressure and 150 parts of water added to the residue which was stood overnight at room temperature. The solid formed was collected by filtration and

dried to yield 19.60 parts of a white crystalline solid having a melting point of 167°-8° C. This solid was shown to contain 80% of 4-methylcarbamoyl-1-methylcarbamoyl-2,2,6,6-tetramethylpiperidine from microanalysis and nuclear magnetic resonance spectra.

EXAMPLE 88

a. 2.65 parts of acrylonitrile was added dropwise with stirring to a solution of 8.55 parts of 1,2,2,6,6-pentamethylpiperidin-4-ol and 0.30 parts of 40% potassium hydroxide solution in 80 parts of benzene. Stirring was continued at room temperature for 16 hours after which time the solution was washed with water, dried and the benzene solvent removed by distillation under reduced pressure. Fractional distillation of the residue, under reduced pressure gave 1.70 parts of 4-(2'-cyanoethoxy)-1,2,2,6,6-pentamethylpiperidine having a boiling point of 105°-6° C. at 0.1 mm of Hg and the following elemental analysis by weight:

	Found	Required (for C ₁₃ H ₂₄ N ₂ O)
Carbon	69.27%	69.60%
Hydrogen	10.69%	10.78%
Nitrogen	12.40%	12.49%

b. To 51 parts of 1,2,2,6,6-pentamethylpiperidin-4-ol a solution of metallic sodium in two parts of tert.butanol was added. 52.5 parts of acrylonitrile was dropped in with rapid stirring. After standing for two days at room temperature the mixture was heated to 80° C. for two hours and distilled under reduced pressure yielding 4-(2'-cyanoethoxy) 1,2,2,6,6-pentamethylpiperidine with a boiling point of 172°-4° C. at 17 mm Hg. This sample was identical to that prepared under Example 88a.

EXAMPLE 89

A mixture of 13.0 parts of 4-dodecyloxy-2,2,6,6-tetramethylpiperidine and 3.42 parts of benzyl bromide was heated at 100° C. for 48 hours. Petroleum ether (b.p. 40°-60° C.) was added to the cooled reaction mixture and the 4-dodecyloxy-2,2,6,6-tetramethylpiperidine hydrobromide formed during the reaction was filtered off. The petroleum ether solvent was removed by distillation under reduced pressure and the residue fractionally distilled to give 4-dodecyloxy-1-benzyl-2,2,6,6-tetramethylpiperidine having a boiling point of 200° C. at 0.5 m.m. of Hg. and the following elemental analysis by weight:

	Found	Required (for C ₂₈ H ₄₉ NO)
Carbon	80.67%	80.90%
Hydrogen	11.82%	11.88%
Nitrogen	3.34%	3.37%

EXAMPLE 90

A mixture of 4-benzyloxy-2,2,6,6-tetramethylpiperidine and 1.67 parts of ethyl α-bromoacetate in 30 parts of ethyl alcohol was heated under reflux conditions for 115 hours. The ethyl alcohol solvent was removed by distillation under reduced pressure and the residue fractionally distilled to give 4-benzyloxy-1-ethoxycarbonylmethyl-2,2,6,6-tetramethylpiperidine having a boiling

point of 145°–6° C. at 0.2 m.m. of Hg. and the following elemental analysis by weight:

	Found	Required (for C ₂₀ H ₃₉ NO ₃)
Carbon	71.62%	72.04%
Hydrogen	8.90%	9.37%
Nitrogen	3.94%	4.20%

EXAMPLE 91

A mixture of 25.7 parts of 1,2,2,6,6-pentamethylpiperidin-4-ol and 3.09 parts of boric acid in 100 parts of toluene was heated under reflux conditions with azeotropic removal of water for 24 hours. The toluene solvent was removed by distillation under reduced pressure to give tris-(1,2,2,6,6-pentamethyl-4-piperidinyl)-borate having a melting point of 83°–9° C. and the following elemental analysis by weight:

	Found	Required (for C ₃₀ H ₆₀ N ₃ O ₃ B)
Carbon	68.85%	69.05%
Hydrogen	11.68%	11.59%
Nitrogen	7.76%	8.06%

EXAMPLE 92

30 parts of 1,2,2,6,6-pentamethylpiperidin-4-ol were dissolved in 250 parts of sodium added. The solution was heated overnight at reflux temperature and then cooled. 38 parts of 2-phenoxyethanol tosylate were added dropwise and the solution heated at reflux for 5 hours. On cooling the precipitate was filtered off and the filtrate evaporated in vacuo. Treatment of the residue with dilute hydrochloric acid and then basification with dilute sodium hydroxide to a pH 10 was followed by extraction with ether. Evaporation afforded a pale yellow oil which was chromatographed on aluminum to give 4-(2'-phenoxyethoxy)-1,2,2,6,6-pentamethylpiperidine as a colourless oil which gave the following elemental analysis by weight:

	Found	Required (for C ₁₈ H ₂₉ NO ₂)
Carbon	72.49%	74.18%
Hydrogen	9.89%	10.03%

-continued-

	Found	Required (for C ₁₈ H ₂₉ NO ₂)
5	Nitrogen	4.91% 4.81%

EXAMPLE 93

10 A mixture of 9.87 parts of 4-allyloxy-2,2,6,6-tetramethylpiperidine and 3.03 parts of allyl bromide was heated at 90° C. for 96 hours. Ether was added to the cooled reaction mixture and the 4-allyloxy-2,2,6,6-tetramethylpiperidine hydrobromide formed during the reaction was filtered off. The ether solvent was removed by distillation under reduced pressure and the residue purified by chromatography to give 4-allyloxy-1-allyl-2,2,6,6-tetramethylpiperidine.

EXAMPLES 94–116

Testing in polypropylene film

15 38 parts of polypropylene were homogenised with 0.076 parts of n-octadecyl-β(4'-hydroxy-3',5'-t-butyl-phenyl) propionate in a kneading machine over a period of 3 minutes at 200° C. 0.19 parts of the product of Example 13 was then added and homogenisation continued for another 7 minutes.

20 This composition was compression moulded into films of 0.1 mm thickness at 260° C. for 6 minutes and the films so obtained were then quenched in cold water.

25 A section measuring 44×100 mm was separated from the 0.1 mm annealed polypropylene foil and exposed to light irradiation in a fadometer device consisting of a circular bank of 28 alternate sunlight and blacklight lamps. The sunlight lamps were 2 feet long, 20-watt fluorescent lamps characterised by a peak emission of 3,100 Angstrom units; the blacklight lamps were 2 feet long, 20-watt ultraviolet lamps characterised by a peak emission of 3,500 Angstrom units. The sample was rotated concentrically about the bank of lamps so that the radiation therefrom was uniformly distributed over the section under test.

30 The exposed sample was examined periodically and portions of it tested for the percent/elongation at break, the time at which the sample reached 50% of the initial elongation at break was noted.

35 Similar tests were carried out on polypropylene samples containing, respectively, no stabiliser and known stabilisers, and also stabilisers falling within the scope of German Patent Specification No. 1,929,928. The results obtained are set out in the following table:

TABLE

Example	Additive	Factor
		Time to 50% of initial elongation at break (additive)
—	none	1.0
—	2-(2'-hydroxy-3',5'-di-t-butylphenyl)-5-chlorobenzotriazole	3.2
—	4-phenylcarbamoyloxy-2,2,6,6-tetramethylpiperidine	1.8
—	1,6-bis[4'-carbamoyloxy-2',2',6',6'-tetramethylpiperidine]hexane	2.4
—	2,2,6,6-tetramethylpiperidyl-4-benzoate	2.6
—	bis(2,2,6,6-tetramethyl-4-piperidinyl)sebacate	4.7
94	1,2,2,6,6-pentamethylpiperidyl-4-phenylacetate	5.2
95	bis(1,2,2,6,6-pentamethyl-4-piperidinyl)terephthalate	5.3
96	1,2,2,6,6-pentamethylpiperidyl-4-(p-methoxybenzoate)	5.3
97	1,2,2,6,6-pentamethylpiperidyl-4-(1'-naphthoate)	5.4
98	1,2,2,6,6-pentamethylpiperidyl-4-octanoate	6.2

TABLE-continued

Example	Additive	Factor
		Time to 50% of initial elongation at break (additive)
99	1,2,2,6,6-pentamethylpiperidinyl-4-isobutyrate	6.2
100	bis(1,2,2,6,6-pentamethyl-4-piperidinyl)sebacate	8.0
101	2,4-bis[4'-carbamoyloxy-1',2',6',6'-pentamethyl(piperidine)toluene	5.2
102	4-p-tolylcarbamoyloxy-1,2,2,6,6-pentamethylpiperidine	5.2
103	4-allylcarbamoyloxy-1,2,2,6,6-pentamethylpiperidine	5.5
104	4-phenylcarbamoyloxy-1,2,2,6,6-pentamethylpiperidine	5.6

106	1,6-bis[4'-carbamoyloxy-1',2',6',6'-pentamethyl(piperidine)]hexane	9.2
107	bis(1-benzyl-2,2,6,6-tetramethyl-4-piperidinyl)sebacate	5.0
108	1-ethoxycarbonylmethyl-2,2,6,6-tetramethylpiperidinyl-4-(p-methoxybenzoate)	5.1
109	1-benzyl-2,2,6,6-tetramethylpiperidinyl-4-(2'-ethylhexanoate)	5.2
110	1-(n-dodecyl)-2,2,6,6-tetramethylpiperidinyl-4-octanoate	5.2
111	1(2'-hydroxyethyl)-2,2,6,6-tetramethylpiperidinyl-4-octanoate	5.8
112	1-(n-propyl)-2,2,6,6-tetramethylpiperidinyl-4-octanoate	6.0
113	4-(n-dodecyloxy)-1,2,2,6,6-pentamethylpiperidine	5.5
114	4-(3'-cyanoethoxy)-1,2,2,6,6-pentamethylpiperidine	>6.0
115	1,4-bis(1',2',2',6',6'-pentamethyl-4'-piperidinyl)butane	>6.0
116	Tris(1,2,2,6,6-pentamethyl-4-piperidinyl)borate	5.0

EXAMPLES 117 to 119

The procedure described in Examples 94-116 was repeated except that 0.25% by weight of the light stabiliser under test was used, and, instead of polypropylene, a low-density polyethylene was employed as substrate.

The pressing was conducted at 180° C. and the pressings were compression-moulded into 1 mm. thick plaques at 150° C.

The plaques were stored at 20° C. and were periodically examined visually for the first sign of exudation.

The results obtained are summarised in the following Table which also includes data relating to comparative experiments (known light stabilisers added).

TABLE

Ex- ample	Light stabiliser added	Time to exudation (days)
—	2,2,6,6-tetramethylpiperidinyl-4-stearate	15
—	bis(2,2,6,6-tetramethyl-4-piperidinyl)sebacate	20
—	4-stearylcarbamoyloxy-2,2,6,6-tetramethylpiperidine	13
117	1,2,2,6,6-pentamethylpiperidinyl-4-stearate	>50
118	bis(1,2,2,6,6-pentamethyl-4-piperidinyl)sebacate	>50
119	4-stearylcarbamoyloxy-1,2,2,6,6-pentamethylpiperidine	>50

EXAMPLES 120 to 122

The procedure described in Examples 117 to 119 was repeated except that the compression moulding was carried out at 200° C. and the substrate used was high-density polyethylene.

The results obtained are set out in the following Table, which also contains data relating to comparative experiments (using a known light stabiliser).

TABLE

Ex- ample	Light Stabiliser	Time to exudation (days)
—	2,2,6,6-tetramethylpiperidinyl-4-	40

TABLE-continued

Ex- ample	Light Stabiliser	Time to exudation (days)
120	stearate 1,2,2,6,6-pentamethylpiperidinyl-4-stearate	>75
121	4-stearylcarbamoyloxy-1,2,2,6,6-[tetr]pentamethylpiperidine	>75
122	1-(n-dodecyl)-2,2,6,6-tetramethylpiperidinyl-4-octanoate	>75

EXAMPLES 123 to 128

100 Parts of crystal polystyrene pellets were dry blended with 0.25 part of 1,2,2,6,6-pentamethylpiperidinyl-4-stearate, and the dry blend was homogenised by [extension] extrusion. The stabilised pellets so obtained were injection moulded to form plaques 2 mm. thick. These plaques were exposed for 3000 hours in a "Xenotest 150" exposure unit, and any yellowing of the plaques was measured by determining the yellowness factor by means of the following equation:

$$50 \quad \text{yellowness factor} = \frac{\Delta T_{(420)} - \Delta T_{(680)}}{T_{(560)}} \times 100$$

wherein the ΔT values represent the transmission loss of the sample at wavelength of 420 [m]nm. and 680 [m]nm. respectively, after exposure in the Xenotest unit, the $T_{(560)}$ represents the transmission value of an unexpected sample at a wavelength of 560 [m]nm.

The results obtained, as well as the results relating to a control experiment and other compositions of this invention are recording in the following Table.

TABLE

Example	Light stabiliser	Yellowning factor after 3000 hours
—	none	35.0
123	1,2,2,6,6-pentamethylpiperidinyl-4-stearate	10.0
124	1-benzyl-2,2,6,6-tetramethylpiperidinyl-4-(2'-ethylhexanoate)	9.8

TABLE-continued

Example	Light stabiliser	Yellowing factor after 3000 hours
125	1,2,2,6,6-pentamethylpiperidinyl-4-(n-octanoate)	9.5
126	4-(2'-cyanoethoxy)-1,2,2,6,6-pentamethylpiperidine	8.0
127	4-stearylcarbamoyloxy-1,2,2,6,6-pentamethylpiperidine	7.5
128	bis(1,2,2,6,6-pentamethyl-4-piperidinyl)sebacate	6.6

EXAMPLES 129 To 132

25 parts by weight of a polyester-based film-forming polyurethane were dissolved in 75 parts by weight of a 1:1 mixture (by volume) of dimethylformamide and acetone, and 1% by weight of 4(2'-cyanoethoxy)-1,2,2,6,6-pentamethylpiperidine was added.

The clear and homogeneous solution was drawn out on a glass plate to a film of 400-500 μ thickness, which was then dried as follows:

at 50° C. for 4 minutes

at 140° C. for 6 minutes

5

10

15

20

25

phenyl) propionate and 2 parts by weight of 1,2,2,6,6-pentamethyl-4-piperidinyl-(3',5'-di-t-butyl-4'-hydroxy) benzoate. The dry-blend was extruded at cylinder temperatures of from 180° to 220° C., and the resulting strand was granulated. The stabilised formulation so obtained was melt-spun and stretched under the following conditions:

Extruder temperatures	230/265/275° C.
Melting temperature at the dye	270° C.
Spinning speed	400 m./minute
Stretching Ratio	1:5
Titer of Multifilament	130/137 denier
Tensile Strength	6 g./denier

TABLE

Example No.	Light Stabiliser	Time (T) to 50% retained tensile strength	Factor T stabilizer / T control
none	none	430	1.0
	2-(2'-hydroxy-3',5'-di-t-butylphenyl)-5-chlorobenzotriazole	530	1.2
133	1,2,2,6,6-Pentamethyl-4-piperidinyl-(3',5'-di-t-butyl-4'-hydroxy benzoate)	1,400	3.3
134	1,2,2,6,6-Pentamethyl-4-piperidinyl- β -propionate	1,600	3.7
135	Bis(1,2,2,6,6-pentamethyl-4-piperidinyl)sebacate	2,600	6.0

The final thickness of the film was 80-100 μ .

The dried film samples were removed from the glass plate, mounted on white cardboard and exposed in a "Xenotest 450" exposure unit, one half of the exposed sample being covered to facilitate subsequent visual estimation of yellowing due to exposure. The sample was controlled and rated visually at intervals of 100 hours.

The data obtained are set out in the following Table which also includes data relating to a control experiment (no added light stabiliser) and to other experiments using stabilisers of this invention.

40

45

50

EXAMPLES 136 to 144

The procedure described in Examples 94 to 116 was repeated except that the annealed polypropylene specimens were exposed to light irradiation in a Xenotest 450 exposure unit rather than in the fadometer device.

The result obtained are summarised in the following Table which also includes data relating to a control experiment (no added light stabiliser) and a comparative experiment (a known light stabiliser added).

TABLE

Example	Light Stabiliser	Time to onset of yellowing (hours)
—	none	<100
129	4-(2'-cyanoethoxy)-1,2,2,6,6-pentamethylpiperidine	200
130	1,2,2,6,6-pentamethyl-4-octanoate	300
131	bis(1,2,2,6,6-pentamethyl-4-piperidinyl)sebacate	300
132	4-phenylcarbamoyloxy-1-n-propyl-2,2,6,6-tetramethylpiperidine	400

65

EXAMPLES 133-135

1000 Parts by weight of unstabilised polypropylene powder were thoroughly dry-blended with 1 part by weight of n-octadecyl- β -(4'-hydroxy-3',5'-di-t-butyl-

TABLE

Example	Light Stabiliser	Time to Failure (hours)
—	none(control)	800
—	2-(2'-hydroxy-3',5'-di-t-butylphenyl)-5-chlorobenzotriazole	1630
136	bis(1,2,2,6,6-pentamethyl-4-piperidinyl)sebacate	>9000
137	1,2,2,6,6-pentamethylpiperidinyl-4- β -(3',5'-di-t-butyl-4'-hydroxyphenyl)propionate	10,000
138	1,2,2,6,6-pentamethylpiperidinyl-4-(3',5'-di-t-butyl-4'-hydroxy benzoate)	>8600
139	1,2,2,6,6-pentamethylpiperidinyl-4-octanoate	6500
140	4-phenylcarbamoyloxy-1,2,2,6,6-pentamethylpiperidine	>7000
141	4-methylcarbamoyloxy-1,2,2,6,6-pentamethylpiperidine	6000
142	1,2,2,6,6-pentamethylpiperidinyl-4-	>6000

TABLE-continued

Ex- ample	Light Stabiliser	Time to Failure (hours)
	cyclohexane-carboxylate	
143	1,2,2,6,6-pentamethylpiperidiny-4-stearate	>6000
144	1,2,2,6,6-pentamethylpiperidiny-4-benzoate	>5000

EXAMPLES 145-150

100 Parts by weight of polyamide-6 pellets containing 1.8 parts by weight of TiO_2 were dry-blended with 0.5 part of 4-benzyloxy-1,2,2,6,6-pentamethyl piperidine. The resulting mixture was melt-spun directly into monofilaments of 20 denier. The monofilaments were mounted on white cardboard without tension and were exposed to light radiation in a Xenotest 450 exposure unit.

After 500, 1,000, 1,500 and 2000 hours of exposure time respectively, 5 fiber samples of each formulation and time interval were tested for tensile strength. The arithmetic mean percentage values of residual tensile strength were plotted as a function of exposure time. The failure points - time to 50% loss of original tensile strength—were obtained from these graphs.

TABLE

Ex- ample	Light Stabiliser	Time to 50% loss of original ten- sile strength (hours)
—	none (control)	475
145	4-benzyloxy-1,2,2,6,6-penta- methylpiperidine	1420
146	bis(1,2,2,6,6-pentamethyl-4- piperidiny)sebacate	1600
147	1,2,2,6,6-pentamethylpiperi- diny-4-octanoate	1450
148	[1]4-phenylcarbamoyloxy-1,2,2,6,6- pentamethylpiperidine	1450
149	1,6-bis(4'-carbamoyloxy-1',2'- 2',6',6'-pentamethylpiperidine) hexane	
150	1,4-bis(1',2',2',2',6',6'-penta- methyl-4'-piperidinyloxy)butane	1600
		1600

What we claim is:

1. A compound having the formula:

wherein [R^I and R^{II} are the same or different and each is a straight or branched alkyl group, having from 1 to 4 carbon atoms, or R^I or R^{II}, together with the carbon atom to which they are each attached form a cycloalkyl group having from 5 to 12 carbon atoms;] Y is [an] alkyl [group, having] of from 5 to 20 carbon atoms, alkenyl [having] of from 2 to 20 carbon atoms, or aralkyl of from 7 to 9 carbon atoms, n is 1 or 2, and R, when n is 1, is hydrogen, alkyl of 1 to 20 carbon atoms, alkenyl of 2 to 20 carbon atoms, cycloalkyl of 5 to 12 carbon atoms, aralkyl of 7 to 14 carbon atoms, 3,5-di-t-butyl-4-hydroxyphenyl, 3,5-di-t-butyl-4-hydroxybenzyl, 2-(3,5-di-t-butyl-4-hydroxyphenyl)ethyl or aryl of 6 to 12 carbon atoms, unsubstituted or substituted by alkyl of 1 to 4 carbon atoms, alkoxy of 1 to 4 carbon atoms or halo or, when n is 2, alkylene having from 1 to 20 carbon atoms, cycloalkylene having from 5 to 12 carbon atoms, arylene of 6 to 20 carbon atoms, vinylene, propylene, p-xylylene, [the group] —CH₂CH₂SCH₂CH₂— or R is [absent] a carbon-carbon bond; [and] or a salt thereof selected from phosphate, carbonate, sulfate, chloride, acetate, stearate, maleate, citrate, tartrate, oxalate, benzoate and substituted carbamate.

2. A compound as claimed in claim 1 wherein R, when n is 1, is hydrogen, methyl, ethyl, n-propyl, isopropyl, n-butyl, sec-butyl, t-butyl, n-pentyl, 2-methylbutyl, n-hexyl, 2-methylpentyl, n-heptyl, 2-ethylpentyl, n-octyl, 2,2,4-trimethylpentyl, n-decyl, n-undecyl, n-tridecyl, n-pentadecyl, n-heptadecyl, eicosyl, vinyl, α -methylvinyl, β -methylvinyl, dec-9-enyl, heptadec-8-enyl, cyclopentyl, cyclohexyl, methylcyclohexyl, t-butyldicyclohexyl, cyclododecyl, 1-perhydronaphthyl, 2-perhydronaphthyl, adamantlyl, cyclopentylmethyl, cyclohexylmethyl, β -cyclohexylethyl, 1-(perhydronaphthyl)methyl, 2-(perhydronaphthyl)methyl, β -[1-perhydronaphthyl]ethyl, β -[2-perhydronaphthyl]ethyl, benzyl, β -phenylethyl, 1-naphthylmethyl, 2-naphthylmethyl, β -[1-naphthyl]ethyl, β -[2-naphthyl]ethyl, phenyl, o-tolyl, n-tolyl or p-tolyl, o-ethylphenyl, m-ethylphenyl, p-ethylphenyl, o-isopropylphenyl, m-isopropylphenyl, p-isopropylphenyl, o-t-butylphenyl, m-t-butylphenyl, p-t-butylphenyl, phenylphenyl, 4-methyl-1-naphthyl, 4-ethyl-1-naphthyl, 4-isopropyl-naphthyl, 4-t-butyl-1-naphthyl, 3,5-di-t-butyl-4-hydroxyphenyl or 2-(3,5-di-t-butyl-4-hydroxyphenyl)ethyl or, when n is 2, [and R] is [a] methylene 1,2-ethylene, 1,4-butylene, 1,8-n-octylene, 2,2,4-trimethyl-1,4-butylene, 1,10-n-decylene, 1,2-eicosylene, vinylene, propylene, 1,2-cyclohexylene, 1,3[or]cyclohexylene, 1,4-cyclohexylene, [cyclohexyl-3-ene,] 1,2-phenylene, 1,3[or]phenylene, 1,4-phenylene, p-xylylene, 1,4-[or]naphthylene, 1,5-naphthylene, diphenylene, [or] diphenylmethylenes [residue] or [the group] —CH₂CH₂SCH₂CH₂— or R is [absent] a carbon-carbon bond.

3. A compound of claim 2 wherein R^I and R^{II} are methyl.
